UNITED STATES PATENT OFFICE

2,081,910

FORMING MACHINE

Harold C. Coppins, Buffalo, N. Y., assignor to
F. N. Burt Company, Limited, Toronto, Ontario, Canada, a corporation of Ontario, Canada

Application December 3, 1932, Serial No. 645,550
Renewed April 1, 1937

83 Claims. (Cl. 93—40)

This invention relates to a forming machine capable of use in numerous different associations, but primarily intended to be employed in connection with the manufacture of receptacles, and 5 specifically paper boxes.

It is an object of the invention to furnish an apparatus which, viewed from one specific aspect, will provide a machine commonly known as a wrap machine capable of expeditiously forming 10 large numbers of receptacles with minimum of manual attention, and by means of which perfect work will result.

A further object of the invention is that of providing a grouping of apparatus, the individual 15 units of which are preferably assembled to achieve a result such as outlined, but which individual units are capable—in certain instances—of advantageous employment as segregated units, or in conjunction with mechanisms other than those hereinafter illustrated and described.

Another object is that of providing a forming 20 machine which will turn out perfect work and in which, if any failure of material supply occurs, the machine will not jam or become otherwise injured or inoperative.

With these and other objects in mind, reference is had to the attached sheets of drawings in which a specific embodiment of the invention has been illustrated as comprising two main units, 25 each in the form of turrets, and to the first of which material in the form of a blank is fed. Thereafter, mechanisms in association with the turret break down the body of the blank; apply a stay strip to such blank; associate a covering sheet with the unit and firmly fold such covering 30 sheet into contact with the unit. Thereafter the unit is transferred to the second turret and mechanisms cooperate with the latter to assure the complete application of the covering sheets to the body of the receptacle, which latter in complete 35 form is finally discharged from the second mandrel.

The invention will now be described with reference to the drawings, of which:

Fig. 1 is a plan view of the improved machine; 45 Fig. 2 is an elevation of the upper and lower drive shafts of the machine;

Fig. 3 is a sectional plan view along the line 3—3 of Fig. 2;

Fig. 4 is a section along the line 4—4 of Fig. 3; 50 Fig. 5 is a front elevation showing the main drive and shafts;

Fig. 6 is a sectional view along the line 6—6 of Fig. 5;

Fig. 7 is a plan view of the blank forming the 55

base of a box manufactured according to this invention;

Fig. 8 shows the first step in the manufacturing operation, i. e., the breaking down of the sides of the body blank;

Fig. 9 is a similar view showing the stay strip in place;

Fig. 10 is a plan view of the covering blank;

Fig. 11 shows the covering blank glued to body blank and two of the sides turned over;

Fig. 12 shows the side extensions of the cover blank folded in;

Fig. 13 shows the remaining two sides of the cover blank folded over;

Fig. 14 is a cross section showing the edge of the cover blank turned in;

Fig. 15 is a perspective view of the finished box;

Fig. 16 is a detail plan view of the body blank feeding means;

Fig. 17 is a detail of the rock shaft for operating the body blank feed;

Fig. 18 is a detail at right angles to Fig. 17 showing the cam and its connections for controlling the rock shaft;

Fig. 19 is a side view of the body blank feeding means;

Fig. 20 is a sectional view along the line 20—20 of Fig. 19 showing the blank grippers and their connections;

Fig. 21 is a side view of the cam and its connections for operating the swinging table;

Fig. 22 is a side view of the cam and connections for rocking the grippers;

Fig. 23 is a detail in side elevation of the body blank folding mechanism;

Fig. 24 is a cross section along the line 24—24 of Fig. 23;

Fig. 25 and Fig. 26 (Sheet 7) are side views of the cams for operating the body blank folding mechanism;

Fig. 27 is a detail in side elevation of the stay strip applying means;

Fig. 28 is a view looking at the opposite side of Fig. 27 and showing the cutter operating mechanism;

Fig. 29 is a detail in side view of the adhesive applying mechanism for the strip;

Fig. 30 is a plan view with parts in section of the suction control for the mandrels of the first turret;

Fig. 31 is a section along the broken line 31—31 of Fig. 30;

Fig. 32 is a view on a smaller scale in continuation of Fig. 31 downwardly and showing the mech-

anism for rotating the mandrels at the stay strip applying station;

Fig. 33 (Sheet 10) is a front view of one of the mandrels;

Fig. 34 is a detail in side elevation of the cover blank applying turret, blank supply and adhesive applying means;

Fig. 35 is a detail elevational view looking at the opposite side of Fig. 34 and showing the mechanism for extending the grippers;

Fig. 36 is a partial sectional view of one of the grippers in pick-up position;

Fig. 37 is a side view of the cam and connections for operating the grippers;

Fig. 38 is a front view of one of the pneumatic grippers;

Fig. 39 is a cross section along the line 39—39 of Fig. 38;

Fig. 40 is a plan view of the cover blank applying turret;

Fig. 41 is an enlarged cross section along the line 41—41 of Fig. 40 and shows the suction control channels;

Fig. 42 is a view showing the mechanism for intermittently rotating the cover blank applying turret;

Fig. 43 is a view showing the chain drive for rotating the adhesive rollers;

Fig. 44 (Sheet 14) shows the cam and connections for actuating the glue sweeper;

Fig. 45 shows the cam and connections for shifting the suction control ring shown in Fig. 41;

Fig. 46 shows the cam and connections for operating the compressed air valve for keeping the blanks separated;

Fig. 47 shows the cam and connections for actuating the mechanism for lifting the blank supply table;

Fig. 48 shows the cam and connections for actuating the swinging glue roller;

Fig. 49 (Sheet 16) shows the mechanism for automatically locking the glue roller;

Fig. 50 is a cross section along the line 50—50 of Fig. 49 and shows one of the teeth of the glue sweeper comb in position;

Fig. 51 is an elevation of the blank retainer and compressed air nozzles;

Fig. 52 is a section through one of the nozzles;

Fig. 53 is a sectional side view of the upper and lower folding rollers;

Fig. 54 is a front elevation of the upper and lower folding rollers;

Fig. 55 shows the cam and connections for operating the upper and lower folding rollers;

Fig. 56 is a partial sectional detail view of the cover blank folding mechanism;

Fig. 57 is a front elevation of the cover blank folding mechanism;

Fig. 58 is an elevational view looking at the opposite side of the mechanism shown by Fig. 57;

Fig. 59 is a cross section along the line 59—59 of Fig. 56;

Fig. 60 shows the crank and lever for shifting the folding means;

Fig. 61 shows the cam and connections for oscillating the presser plate;

Fig. 62 shows the cam and connections for actuating the corner folding rollers;

Fig. 63 is a plan view of the side folding mechanism;

Fig. 64 is a sectional view of the side folding mechanism along the line 64—64 of Fig. 63;

Fig. 65 shows the cam and connections for operating the side folding rollers;

Fig. 66 shows the cam and connections for ac-

tuating the mechanism for taking the box off the mandrel of the first turret;

Fig. 67 is a partial sectional side view of the second turret;

Fig. 68 (Sheet 20) is a partial plan view of the second turret;

Fig. 69 is a front elevation of one of the mandrels of the second turret;

Fig. 70 (Sheet 22) is a horizontal section at the shifting track for extending the mandrels;

Fig. 71 is a detail in side elevation of the track shift operating mechanism;

Fig. 72 is a detail in side elevation of the mechanism for turning in the edge of the cover blank;

Fig. 73 is a sectional rear view of the mandrel 15 along the line 73—73 of Fig. 72;

Fig. 74 is a section along the line 74—74 of Fig. 72 looking in the direction of the arrows;

Fig. 75 is a front view of the mandrel expanded;

Fig. 76 is a sectional view of part of the mandrel 20 along the line 76—76 of Fig. 73 looking in the direction of the arrows;

Fig. 77 shows the cam and connections for actuating the mechanism for expanding and contracting the mandrel;

Fig. 78 shows the cam and connections for shifting the mandrel away from and towards the second turret;

Fig. 79 is a side view of the stripping mechanism for removing the box from the mandrel;

Fig. 80 is a side view of the cam and connections for moving the stripper towards and away from the second turret, and

Fig. 81 (Sheet 3) is a side view of the cam and connections for operating the gripping mechanism.

In the present embodiment of the invention a suitable supporting frame is provided, comprising upper and lower tables 1 and 2 and supporting legs 3 for the tables. Two turrets are mounted on the frame and the said turrets are distinguished as the first and second. The first turret comprises a shaft 4 having on the upper end thereof a hub 5, which has radial arms 6 and the arms are bored axially to provide passages 7 for a purpose to be presently set forth.

A box mandrel or former 8 is supported by each arm, and in the present instance there are six arms, so that the turret carries six mandrels or formers. Each mandrel 8 comprises a body 8' and a top or face 9 secured to the body by screws 10. The body 8' is rigidly connected with a sleeve 11 journaled on a hollow screw member 12 carried by the arm. The hollow screw member registers with the passage 7 of the arm.

The sides 13 and ends 14 of the body 8', and the face 9 of each mandrel are grooved longitudinally and transversely as shown at 15 of Fig. 33, all grooves communicating by passages 16 with a hollow cylindrical part 17 of the body 8' in which the passage 7 terminates also, so as to provide the mandrels with pneumatic gripper faces for holding the body blanks thereon. The sleeve 11 is provided at its inner end with a spur wheel 18 whose outer face is frictionally engaged by the flange of a bracket 19 secured to the arm 6, and thereby holding the mandrel against said arm, but rotatably in relation to the same. Normally, the sleeves are held from rotation, and in fixed position with respect to the arms, by means of locking levers 20. These levers are elbow levers and each is pivoted on the under side of the arms 23 adjacent to the hub. The end of the arm 23 of each lever is adapted to engage in a notch 21 in the hub of the spur 75

10

25

30

40

45

55

60

65

70

75

wheel 18, to prevent rotation of the sleeve and mandrel. The lever 20 is normally held in engagement with the spur wheel, by means of a coil spring 22 arranged between the arm 8 and the upper arm 23 of the elbow lever 20. Each lever 20 constitutes a lock which normally holds the adjacent sleeve and mandrel from rotation, and in a fixed position with respect to the table.

A step by step movement is imparted to the first turfet from a countershaft 24, which in turn is driven in a manner to be presently described, through a Geneva stop movement. This movement comprises a gear wheel 25 keyed to shaft 4, and a mutilated gear 26 secured to a vertical shaft 27 and driven through a bevel gear connection 28 from the countershaft 24. The gear wheel 25 which is also a mutilated gear has six series of teeth and between each series there is a concave portion indicated at 29. The mutilated gear 26 has one series of teeth and at each end of the series a rib 30 is secured radially to the face of the gear. The wheel 25 has six radial arms 31, extending beyond the periphery of the gear wheel, and adapted to engage the ribs 30, which are within the periphery of the gear 26. The arms 31 are at the concave surfaces 29 of the wheel 25, and when that portion of the gear 26 not provided with teeth is in engagement with a concave surface, the wheel 25 is locked from rotation. The ribs 30 are starters, which engage the arms 31 to start the gear 25 when the teeth of the gear 26 come in engagement with a series of teeth on the gear 25. Thus an intermittent movement with periods of rest is imparted to the gear wheel 25 and to the turret shaft 4.

At station I, a body blank is fed or supplied to the mandrel 8, by a mechanism or device shown more particularly in Figs. 16 to 22 inclusive. The said mechanism comprises a magazine including a plate 32 which constitutes the bottom of the magazine and side walls 33. The side walls are connected to the bottom for adjustment toward and from each other by means of screws 34 which pass through slots in angle plates 33^a to which the side walls are attached, into engagement with the plate 32. A pair of rails 35 is arranged at each side of the plate, and each pair is connected to the plate for adjustment toward and from the other pair by screws 36 passing through slots in outwardly extending feet 37 on the outermost rail of the pair. A pusher bar 38 is mounted to move between the members of each pair of rails, and the bars are connected at the end remote from the turret, by means of a cross-head 39. The cross-head is connected to a slide 40 mounted to move in a guideway 41 on the underside of the plate 32 and at the center thereof. The inner members of the pairs of rails are rabbeted on their outer faces and at their upper edges to receive the bars 38, and the inner wall of the rabbet has a longitudinally extending rib engaging a similarly shaped groove in the adjacent bar, thereby to guide the bar. The corner cut blanks A which are cut to shape, each comprising a rectangular body and side and end flaps, adapted to be folded to provide an open rectangular box or tray, rest in a pile upon the rails 35, and they are held in position in the magazine by a gauge bar 42 on the table 32, and by a pair of angle pieces 43, to be presently described. The gauge bar 42 is adjustably connected with the table by a screw and slot connection indicated at 42^a and the angle pieces 43, being fixed to the side walls 33, are automatically adjusted toward and from each other by adjust-

ment of said walls. The end flaps of the blanks rest on the rails, and the angle pieces 43 engage the cut-out corners of the blanks on the side toward the turret. The gauge bar 42 engages back of the pile of superposed blanks, as shown in Fig. 16. The pusher bars 38 extend above the rails 35, a distance corresponding to the thickness of a blank, so that when the pusher bars are moved toward the turret, they will engage the lowermost blank of the pile, and push it out from beneath the pile.

Retaining fingers 44 are arranged at the front of the magazine for preventing the passage of more than a single blank. As shown in Fig. 19, the retaining fingers are adjustably connected to angle pieces 43, supported by the side walls. Each finger is adjustably connected with the adjacent angle plate by screw and slot connections 45, and the lower ends thereof are spaced above the rails, just far enough to permit passage of one blank. The lower, outer corners of the fingers are beveled, and by loosening the screws, the fingers may be adjusted vertically in accordance with the thickness of the blank. The slide 40 is operated by a rock arm 46 pivoted at 47 on the table 1 and having one arm connected by a link 48 with the slide. The other arm of the rock shaft is connected by a link 49 (Figs. 17 and 18) with operating mechanism to be later described.

To prevent sticking and jamming of the blanks in their guides 42 and 43, a pair of grippers 50 is provided, one on each side of the pile of blanks, and each is connected at its upper end by a link 51 to one arm of a rocking lever 52, which is journaled in brackets 53 carried by the magazine members 33. The other arm 54 of the rocking lever is pivotally connected by a link 55 to a rocking lever 56 journaled on the table 1 at 57 and connected by link 58 to an operating mechanism to be later described. Each gripper 50 is provided with teeth 59 and carries a curved leaf spring 60 mounted on the magazine side members 33. The curved leaf springs 60 tend to keep the grippers in contact with the edges of the blanks but permit a slight rocking movement of the grippers, which, by means of their teeth, carry the pile of blanks upwardly for a slight distance and drop them upon the few bottom blanks, which, being below the reach of the grippers, are left undisturbed. The pile of blanks, therefore, is kept moving all the time, thereby eliminating the possibility of sticking, so that a blank will at all times be deposited on the rails 35.

The blanks are fed from the magazine onto a swinging table 61. This table is secured to arm 62 of a rock shaft 63 journaled in a bearing bracket 64 on the table 1, and it is normally spring held in lowered horizontal position by means of a coil spring 65 arranged between another arm 66 on the rock shaft and the bearing bracket 64. The arm 66 is connected by means of an adjustable link 67 with operating mechanism to be later described.

At regular intervals, the table is swung upwardly into the dotted line position of Fig. 19 by the operating mechanism connected with link 67, to present a blank against the outer face of a mandrel 8 which at this time is in alignment with the magazine and swinging table. The swinging table has stops 68 adjustably connected therewith by screw and slot connections 69 and each stop has a portion for engaging the edge of the side flap of the blank. There are also stops

70 adjustably connected to the swinging table by screw and slot connections 71, these stops having portions for engaging the forward edge of the blank.

5 When the swinging table presents a blank to a mandrel 8, the grooves 15 of the mandrel are connected with suitable exhausting mechanism by means of the passage 7, and the body of the blank is held against the mandrel by suction, the 10 flaps of the blank projecting beyond the sides and ends of the mandrel. The mechanism for connecting the passage 7 with a suitable suction apparatus so as to energize and de-energize the grooves 15, is shown more particularly in Figs. 15 30 and 31. This mechanism comprises a valve ring 72 mounted to oscillate on the upper end of the hub 5. The ring has on its under face an arc shaped passage 73 with which communicates a hose 74 from suitable continuously operating exhausting apparatus. When the ring is 20 in the position of Fig. 30, the mandrel 8, from which a box has just been removed, is cut off from the exhausting apparatus. As soon as a box blank is pushed against the mandrel at station I, the ring is oscillated to connect the passage 7 of the mandrel at station I with the groove 73 of the ring, and with the source of fluid pressure. The same operation of oscillating the ring disconnects the passage 7 of the mandrel 8 30 at station VI from the groove 73 of the ring so that there is no suction on the box to interfere with its removal. The blank supplied to the mandrel 8 at station I is held tightly against the mandrel, and the pressure is continued until 35 the box reaches station VI, when the passage 7 is brought out of register with the groove 73, and the pressure is cut off. The ring is oscillated by means of a link 75, pivotally connecting the ring with operating mechanism to be later described. The ring 72 encircles a boss 5^a on the hub and is held tightly against the upper end of the hub by a coil spring 4^a arranged between the stop collar 4^b and the hub. The stop is adjustable to vary the tension of the spring.

45 The turret now advances the mandrel 8 and blank to the second station, where the flaps of the blank are folded onto the sides and ends of the mandrel, to which they are held tightly by suction, provided at these points by grooves 15 and passages 16 in the sides and ends of the mandrel and connecting with the passage 7. The mechanism at station II, as shown in Figs. 23 to 50 26 inclusive, includes a holding plunger 76 of substantially the area of the body blank, which 55 engages the blank on the mandrel, forming a support for the body of the blank while the flaps are folded, so that the body is prevented from outward bulging away from the mandrel during the folding operation. A series of four folding arms 60 77 is provided, one arm for each flap, and each arm carries a plate 78 for engaging the flap to fold the same toward the periphery formed by the sides and ends of the mandrel. Each arm is pivoted between a pair of lugs 79 extending 65 radially from a stem 80, to which the plunger 76 is connected. Each of the arms is adjustable toward and from the stem; that is, toward and from the axis of the mandrel to provide for boxes of different size. The members of each pair of lugs are radially slotted and the pivot bolt 81 of the arm passes through the slots so that by loosening the bolt the arms may be moved toward and from the stem.

70 The arms 77 are operated simultaneously, by 75 means of links 82. Each of these links is piv-

oted between a pair of lugs 83, similar to lugs 79, extending radially from a head 84 mounted to slide longitudinally of the stem, and each of the links is adjustable toward and from the head, to correspond with the adjustment of the arms 77. The members of each pair of lugs 83 are slotted and a pivot bolt 85 is provided to pass through the slots to afford adjustment of the links toward and from the axis of the mandrel similar to the adjustment of the arms 77. 10 The plunger 76 and the arms are moved toward and from the mandrel, and the head 84 moves therewith, and also has relative movement with respect to the stem, so that as the plunger engages the blank, the arms move against 15 the flaps to fold the latter.

The stem 80 is slidable in a bearing 86 and it is moved toward and from the turret by means of an elbow lever 87 pivoted at 88 to an extension 89 of the bearing 86 which supports the 20 stem 80. One arm of the elbow lever is connected to a collar 90 fixed to the stem, by means of a link 91, and the other arm of the elbow lever is connected to one of the arms of another elbow lever 92 pivoted to a bracket 93 on the table 25 1, by a link 94. Operating mechanism to be later described in detail is connected with the other arm of the second elbow lever and a coil spring 95 is arranged between the elbow lever 92 and an extension 96 from the supporting 30 bracket 97 of the bearing 86, the spring acting normally to advance the stem 80 toward the turret.

The head 84 is operated by a somewhat similar mechanism connected to a rod 98 which is 35 slidable in a bearing 99. The bearing 99 is an integral part of bearing 86 and supported by bracket 97. The rod 98, at its end facing the turret, carries a fork shaped plate 100, whose arms 101, as shown in Fig. 24, are adapted to 40 engage shoulders 102 on the head 84, which is slidably connected to the stem 80 by key 103 riding in slot 104 in the stem. In this manner, the head 84 and the stem 80 are prevented from rotating, by the fork plate 100, but the 45 head is free to move longitudinally with respect to the stem. An elbow lever 105 is also pivoted at 88 to the extension 89 before mentioned, and a link 106 connects the upper arm of the lever with a collar 107 on the rod 98. A link 108 connects the other arm of the lever with one of the arms of another elbow lever 109, journaled on bracket 93, and operating mechanism to be later described is connected with the other arm of said elbow lever. A coil spring 110 is arranged between the lever 109 and the extension 96 before mentioned, the spring acting normally to advance the rod 98 toward the turret. 55

The lugs 79 are on a hub which fits on a spindle (not shown) on the end of the stem 80, and the hub is held in place by a nut 111 which engages the reduced threaded end of the spindle. The plunger 76 is carried by a rod 112 which is slidable in an axial opening in the stem, and it is normally spring pressed outwardly by suitable means (not shown), such as a coil spring arranged within the opening, and the movement of the rod being limited by a cross-pin on the rod, which moves in a slot in the stem. 60

The position in which the folding plates 78 will press the flaps of the blank firmly against the sides and ends of the mandrel 8, may be 65 adjusted by a nut 113 engaging the threaded end of the stem 80, remote from the turret, and controlling the position of the collar 90 on the stem, 70 75

and a set screw 114 in the collar is provided to fix the same in position after the adjustment is made. When a mandrel 8 carrying a blank arrives at station II, the stem 80, together with the set of folding plates 78, move toward the turret. The plunger first engages the body of the blank, which will eventually become the bottom of the box, and presses it firmly against the end face of the mandrel, so that there can be no bulging when the folding of the flaps takes place. At the same time, the folding arms are moved toward the turret, and the head is moving with respect to the stem toward the turret, so that the folding plates 78 turn the flaps down upon the sides of the mandrel, with a wiping movement, engaging the flaps at the corners of the mandrel, and folding toward the free edges of the flaps from the corners.

As before mentioned, the flaps are held in this position by suction. The head now moves away from the turret, thereby opening the folding plates away from the sides and ends of the mandrel 8, and the stem then also moves away from the turret into the position shown in Fig. 23, to permit advancement of the mandrel to the next station.

At station III a stay strip B is wound about the folded flaps to hold them in place and reinforce the corners, the stay strip being previously provided with adhesive. The mechanism for applying the stay strip, as shown in Figs. 27 to 29 inclusive, is supported by a bracket 115 mounted on the table 1. The bracket has an inclined extension at one side of its top, and a guideway 116 is adjustably connected to the extension, by a screw and slot connection 117. A carriage 118 is mounted to move on the guideway, and the upper end of the guideway is bevelled to form the blade for a cutter to be described. The cutter includes a slide 119 having guided movement in a vertical direction in a guide 120 on the bracket 115, before mentioned. At its upper end the slide 119 has a laterally arranged head 121, from which extends a pair of vertically spaced jaws 122, the jaws extending above the slide. A cutting blade 123 is secured to the upper jaw, and this blade cooperates with the beveled end of the guideway 116 as a ledger blade, to cut the stay strip, when the slide 119 moves downward. The stay strip indicated at B passes over the carriage 118 from adhesive applying mechanism to be later described, to and between the jaws 122. The strip is held to the upper face of the carriage during the movement of the same, by means of a comb 124, on one end of a resilient plate 125, which is supported at the other end on the upper arm of a substantially U-shaped member 126 which is secured to the carriage. One arm of this member is below the carriage and the other is above and spaced apart from the upper face of the carriage, to permit passage of the stay strip.

The end of the plate 125, remote from the comb, is connected to the U-shaped member 126 by means of a hinge 127 and a coil spring encircles the pin of said hinge, the ends of the spring being so connected that the tension of the spring is exerted to hold the plate 125 with the comb pressed against the strip of paper. The comb, however, may yield on the rearward movement of the carriage, to prevent movement of the strip therewith. A holding pawl 128 is supported by the plate 125 near the hinge connection, the pawl being pivoted to a bracket on the under face of the plate. The arrangement

of the pawl is such that it prevents rearward or outward movement of the strip with respect to the carriage, but permits free forward movement of the strip. When traction is made on the strip rearwardly or outwardly, that is, away from the mandrel 8, the pawl tends to take a vertical position, clamping the strip to the carriage, and the pawl is of considerable width to prevent injury to the strip. The strip is guided on the carriage between two gauge plates 129 adjustably connected therewith, at the end remote from the mandrel, and the carriage is reciprocated by means of a lever 130 pivoted on an extension 131 carried by the bracket 115, and one arm of the lever is connected to the carriage by a link 132, connecting with the U-shaped member 126. The lever 130 is rocked at suitable intervals, to reciprocate the carriage by a cam 133 on a shaft 134 to be later described. The other arm of the lever 130 is connected to one end of a follower 135 embracing the shaft 134 and provided with a friction roller 136 engaging the edge of the cam 133. The roller 136 is held in contact with the cam edge by means of a spring 137 arranged between the upper arm of lever 130 and the bracket 115.

The shaft 134 is journaled in a bearing 138 on the under side of the bracket 115 and the cams are held on the shaft in spaced relation by means of spacing collars and a nut and washer 139. A sprocket wheel 140 is pinned to the end of the shaft 134, remote from nut 139 before mentioned, and a sprocket chain 141 in mesh with sprocket wheel 140 is driven by operating mechanism to be later described.

As shown by Fig. 29, the strip of paper which is supported on a reel 142 is supplied with a coating of adhesive before it passes onto the carriage, and the adhesive is on the upper face of the strip. The reel 142 is supported in brackets 143 depending from a receptacle 144 for adhesive, which, in turn, is supported by an extension 145 from the table 1. From the reel, the strip passes over an adhesive applying roller 146, which is journaled in the receptacle or pan 144, and rotates in the adhesive, and the film of glue on the roller is regulated by a scraper or doctor 147, hinged to the pan and engaging the periphery of the roller. The strip is guided to the roller 146 by guide rollers 148 and excessive adhesive is removed from the strip by a scraper 149. The strip then passes beneath a guide roller 150 and around a roller 151 journaled in the end of an arm 152, pivoted to the frame 145 at 153. A coil spring 154, arranged between the arm and the frame 145, normally tends to swing the roller 151 away from the pan, that is, in a direction to tension the strip. The movement of the roller away from the pan is limited by a lug on the arm, which engages the frame 145.

The roller 151 may yield toward the carriage, when the latter moves toward the mandrel, to prevent injury to the strip, but as soon as the tension on the strip is relaxed, the spring swings the roller to its normal position. In order to prevent injury to the strip by the pull on the reel, and to start the reel by the pull of the strip, thereby to provide slack in the strip between the reel and the adhesive applying means, a roller 155 is provided, which engages the strip adjacent to the reel. This roller is supported by a link 156 which is pivoted to one arm 157 of the reel, the reel as shown having a cross at each end. A spring 158 is arranged between the arm and the link, and the link is so connected to the arm 75

of the cross that it normally holds the position shown in Fig. 29, but may yield to permit the roller 155 to move away from the reel. With this arrangement, when tension comes upon the strip, 5 the lever 156 is first swung by the taut strip, and the lever reacts against the cross arm, thus imparting a movement of rotation to the reel, in a direction to unwind the strip.

When a mandrel comes into register with the 10 stay strip applying means, the carriage 118 is moved toward the mandrel, in a line perpendicular to the axis of the supporting arms, and the free end of the gummed strip is projected above a laying and pressing roller 159, which applies it 15 to the box on the mandrel. This roller is supported by a lever 160 pivoted at 161 to an extension 162 from the bracket 115. This roller is normally swung toward the mandrel by a coil spring 163, arranged between the table 1 and a follower 20 164 on the shaft 134, and pivoted at 165 to the lever 160. The follower has a friction roller 166 engaging the edge of a cam 167, and the cam acts to move the follower and the roller 159 away from the mandrel.

25 As the end of the stay strip passes between the jaws 122 of the slide 119, it is engaged and supported by a roller 168, journaled in an extension 169 from the bracket 115. The roller 168 prevents the end of the strip from dropping down 30 between the roller 159 and the cutter. The carriage is yieldingly held to the guide by means of pins and springs (not shown), depending from the carriage, and passing through longitudinally extending slots in the extension of the guide. This 35 connection permits a limited movement of the carriage with respect to the guide.

As soon as the end of the strip contacts with the box, it is engaged by the roller 159, and the mandrel is rotated by mechanism to be later 40 described. The strip is wound on the box, the roller 159 holding it firmly against the box. The roller may move downwardly to pass the corners of the box on the mandrel, but it is held firmly against the box by the spring, so that the strip 45 is smoothly laid. Just before the mandrel completes its rotation the strip is severed by blade 123 of the cutter. The slide 119 of the cutter has guided movement vertically in the bracket 115 and a lug 110 depends from the lower end 50 thereof. A lever 171 is pivoted to an extension 172 from the lower end of the bracket 115, and the free end of this lever rests upon a cam 173, secured to the shaft 134, and the lower end of lug 110 engages the lever in line with the axis 55 of the shaft. A coil spring (not shown) is arranged between the head 121 and the bracket 115, to normally pull the cutter downwardly. Since the cutting blade 123 engages the gummed face of the strip, a portion of the gum may be transferred thereto, and mechanism is provided on the 60 carriage, to clean the blade. This mechanism is a brush 174 connected with the carriage, with the bristles extending toward the cutter. When the strip moving carriage reaches the end of its 65 movement toward the mandrel, the bristles of the brush engage the cutter blade and remove any gum that may have become attached thereto.

As previously stated, the mandrels 8 are normally held from rotation, being locked, as shown 70 in Fig. 31, by locking levers 20. When the mandrels reach station III, however, these levers are released in a manner to be later described, and a mechanism is engaged with the mandrels to rotate the same.

75 This mechanism, as shown in Figs. 31 and 32,

includes a sleeve 175 mounted below the hub 5, and to slide upward and downward on the turret shaft 4, and having a threaded connection at its lower end with a collar 176. At its upper end, the sleeve 175 is shaped to form a hub 177, and a short arm or eye 178 extends outward and in line with the mandrel at station III. Directly below and in line with the pinion 18, but normally not in mesh with the latter is a gear 179 rotatably mounted on a screw 180, which is securely 10 screwed into the arm 178. The gear 179 at the end of its hub 181 toward the turret, carries a bevel gear 182, which meshes with another bevel gear 183 carried by a sleeve 184 directly below the hub 177 and encircling the sleeve 175, before 15 mentioned. Attached to the sleeve 184 at its lower end is a pinion 185, which is in mesh with a pinion 186 fixed to a vertical shaft 187, and this shaft is made to rotate at regular intervals by a mechanism to be presently described in detail. 20 The sleeve 175, with its hub 177 bearing against the top face of the bevel gear 183, extends through and beyond the sleeve 184 with its bevel gear 183 and its pinion 185, and the collar 176 is screwed onto said sleeve 175 to form a bearing 25 and support for the lower face of the pinion 185. The collar 176, and with it the sleeve 175, is prevented from turning about the shaft 4 by an upright pin 188 in the table 1, which extends through a hole in the collar and permits upward 30 and downward movement of the same.

A link 188 is connected to the collar at 189 and an adjustable rod 190 is connected to the link 188 by slot and pin connection 191. The other end of said rod is connected to an operating 35 mechanism comprising a follower 192 pivoted on a bracket at 193 and carrying a friction roller 194. The friction roller 194 engages the edge of a cam 195 mounted on a horizontal shaft 196, which is continuously driven by means to be later 40 described in detail. The collar 176 is normally held in a lowered position, as shown in Fig. 31, by means of a coil spring 198 arranged between the rod 190 and the table 2, and another coil spring 199 is arranged to encircle the rod and 45 provide a cushioning means between the latter and the link 188. The collar 176 and the mechanism attached thereto moves upward at regular intervals, thereby bringing the pinion 179 in mesh with the pinion 18 of the mandrel. The mechanism 50 remains in this position until the rotation of the mandrel has been completed. As the mechanism just mentioned moves upward, the periphery of the hub 181 of the gear 179 is pressed against the lower end 200 of the arm 23 of 55 the locking lever 20, releasing it against the pressure of the spring 22, and thereby rendering the mandrel 8, which is in position to receive the stay strip, free to be rotated.

As bevel gear 201 is fixed to the lower end of 60 the shaft 187, and said bevel gear meshes with another bevel gear 202 on a shaft 203, as shown in Fig. 3 and Fig. 4. An intermittent movement, with periods of rest, is imparted to the shaft 203 and the shaft 187, by means of a Geneva stop 65 movement. This movement comprises a gear wheel 204, keyed to the shaft 203, and a mutilated gear 205 secured to the countershaft 24 before mentioned. The gear wheel 204 which is also a mutilated gear has a concave portion indicated 70 at 206 (Fig. 4) at one point between its series of teeth. The mutilated gear 205 has a rib 207 secured radially on the face of the gear at each end of its series of teeth. The wheel 204 has a radial arm 208, extending beyond its periphery, 75

and adapted to engage the ribs 207, which are within the periphery of the gear 205. The arm 208 is at the concave surface 206 of the wheel 204, and when that portion of the gear 205 not provided with teeth is in engagement with the concave surface, the wheel 204 is locked from rotation. The ribs 207 are starters, which engage the arm 208, to start the wheel 204 when the teeth of the gear 205 come into engagement with the teeth on the gear 204. Thus, an intermittent movement is imparted to the shaft 203 and the shaft 187 and the mandrel 8 at station III is rotated by means of the mechanism previously described. The collar 176 normally rests on the face of the table 1 and the pinion 186 on the shaft 187 is of sufficient length longitudinally to permit upward movement of the mandrel rotating mechanism, without getting out of mesh with the pinion 185.

20 The mechanism rotating the mandrel 8 moves downward and into its original position after the rotation has been completed, thereby permitting the locking lever 20 to again lock the mandrel in position. The mandrel has performed a complete rotation so that the notch 21 will be in line with the lever 20 to permit locking, and the mandrel is then moved by the turret to the succeeding or fourth station.

At station IV a cover blank C is attached to the box on the mandrel 8, the cover blank being previously provided with adhesive, and the upper and lower flaps of said cover blank are folded onto the corresponding flanges of the box on the mandrel. The mechanism for attaching the cover sheet, as shown in Figs. 34 to 52 inclusive, includes a turret generally indicated at 209, intermittently rotating in a vertical plane. The turret carries four mandrels 224, to be later described, having pneumatic gripper faces. Each of these mandrels in its lowest position picks one cover blank off the top of a magazine of cover blanks generally indicated at 210. On its rotary path to the next position, a glue roller 302 rises from an adhesive supply pot 211, and the cover blank on the mandrel of turret 209 is wiped against the glue roller, which has a device to apply adhesive in stripes. Finally, the mandrel is projected radially toward the first turret, to carry the glued cover blank against the bottom of the box on the former.

50 The turret 209 includes a horizontal shaft 212, rotatably mounted in bearings 213 and 214, supported by brackets 215 from the table 1, and a disc 216 having four radially extending and substantially U-shaped channels 217, is mounted on said shaft by a pin 218.

Adjacent the face of said disc, toward the bearing 213, is another disc 219, fixed to a bushing 220 by means of a set screw 221, the bushing 220 encircling the shaft 212, and fixed to the bearing 213 by a lug and bolt connection at 222, rendering said bushing and the disc 219 attached thereto, stationary with respect to the shaft 212, which is free to rotate within the bushing. Slidably mounted in each of the channels 217 is a slide member 223, which carries at its outer end a mandrel 224. A roller 225 (see Figs. 35 and 36) mounted on the end of each slide member 223 toward the shaft, is guided in an annular groove or track 226 provided in the disc or flange 219. The engagement of the rollers with the groove prevents outward movement of the members 223 of the mandrel, except when the mandrel is in a position to pick up or deposit a cover blank. At these points, a switch plate 227 is interposed in

the trackway 226, being arranged in a radial recess 228 in the disc 219, and having a groove 229 in its face concentric with the shaft 212, for receiving the roller 225 of that mandrel which is in line with said switch plate.

5 As before mentioned, the switch plates are arranged at the pick-up and at the depositing station, that is, a switch plate 227 is in the lowest vertical position of the mandrel 224, and another switch plate is provided in a horizontal position, pointing to and being in line with the mandrel of the first turret at station IV. Each of the switch plates 227 is connected to one arm of an elbow lever 230 by a link 231, the elbow lever being pivoted to the disc 219 at 232, and the other arm of said lever is connected to a lug 233 on a sleeve 234, by a link 235. The sleeve 234 is journaled on the bushing 220 and carries at its end remote from the disc 219 a lug 236 which is connected by a link 237 to operating 20 mechanism to be later described in detail.

A step by step motion is imparted to the turret 209 by a Geneva stop movement including a gear wheel 238 on the shaft 220, and a mutilated gear 239 mounted on a shaft 240. The shaft 240 is 25 mounted in a bearing bracket (not shown) on the table 1 and carries a sprocket wheel 241 driven by a sprocket chain 242 from a sprocket wheel 243 on a counter shaft 244 which, in turn, is driven by a mechanism to be later described. The gear wheel 238 (Fig. 42), which is also a mutilated gear, has four series of teeth and between each series there is a concave portion indicated at 245. The mutilated gear 239 has one series of teeth, and at each end thereof a rib 246 is secured radially on the face of the gear. The wheel 238 has four radial arms 247, extending beyond the periphery of the gear wheel, and adapted to engage the ribs 246, which are within the periphery of the gear 239. The arms 247 are at the concave surfaces 245 of the wheel 238, and when that portion of the gear 239 not provided with teeth is in engagement with a concave surface, the wheel 238 is locked from rotation. The ribs 246 are starters to start the wheel 238 when the teeth of gear 239 come into engagement with a series of teeth on the gear 238. In this manner an intermittent movement with periods of rest is imparted to the gear wheel 238 and the turret shaft 220.

50 As previously mentioned, there are four mandrels 224 arranged in a cross, each including a movable and a stationary part. The pneumatic grippers embodied in the mandrels 224 (Figs. 38 and 39) are of substantially the same area as 55 the cover blank, and each includes a movable plate or body 248 of a size corresponding with the body area of the cover blank, said body 248 being mounted on the slide 223 by brackets 249. A gripper 250 at the leading edge and a plate 251 at 60 the trailing edge of the blank are mounted on stationary extensions 252 and 253 respectively, from the disc 216. A plate 254 having suction openings 255 is mounted on the body 248 by means of screws 256, and said body has a recess 257 in 65 its face to form a suction chamber between the face plate 254 and the body 248. A hose 258 connects the suction chamber 257 with a passage 259 in the disc 216, which leads to a suction control valve to be later described in detail. The gripper 70 250 at the leading edge of the cover blank is of the same area and shape as the extension of the cover blank which it engages. Said gripper also is of the pneumatic type and comprises a face plate 260 whose suction openings 261 connect 75

with a chamber 262 formed by the body 263 to which the top is secured by means of screws 264, and a hose 265 which connects the chamber with a passage 266 in the disc 216, said passage leading 5 to a suction control valve to be later described.

The plate 251 before mentioned has no suction openings but is of the same area and shape as the trailing extension of the cover sheet, and merely furnishes a support for the same. In this 10 manner a pneumatic gripper is provided which can move radially outward from the turret to engage and grip the top sheet of a pile of cover blanks, and hold the same until the suction is cut off.

15 The mechanism for connecting the passages 259 and 266 with a suitable continuously operating suction apparatus so as to energize and de-energize the openings 255 and 261 is shown more particularly in Fig. 40 and Fig. 41. This mechanism 20 comprises a valve ring 267 mounted to oscillate on the face of the disc 216. The ring has on its face toward the disc two arc shaped passages 268 and 269, and a common passage 270 connects the passages 268 and 269 with hose 271, 25 communicating with a suitable exhausting apparatus. When the ring is in the position of Fig. 41, the turret 209 has just completed one step of its intermittent movement, and there is a mandrel 224 in line with each of the switch plates 30 227 ready to be radially moved outward. The passage 266 leading to that mandrel which is in a horizontal position and toward the mandrel 8 carrying the box or body blank, has been cut off shortly before that mandrel arrived in this position, whereby the gripper 250 has released its grip 35 on the cover blank extension, but the suction on the movable gripper is still on. Both passages 259 and 266 leading to the mandrel in pick-up position, are cut off from the source of suction. The 40 two mandrels 224 referred to are now simultaneously moved radially outward, and the mandrel carrying the cover blank, to which adhesive has been applied by a mechanism to be later described in detail, deposits the blank on the bottom of the 45 box on the mandrel 8, while the other mandrel 224 engages the top sheet of the pile 210 of cover blanks. The ring 267 is now oscillated to connect the groove 268 with the passage 259 and the groove 269 with the passage 266 leading to the 50 mandrel which is engaging the cover sheet, whereby connection is established between the suction openings in the gripper and the source of vacuum.

The cover sheet is therefore pneumatically 55 gripped and held to the gripper. The oscillating movement referred to of the ring 267 has at the same time disconnected the groove 268 from the passage 259 leading to the mandrel in depositing position, thereby cutting off the suction from its 60 gripper, and the cover blank is thus released and is glued to the bottom of the box body blank on the mandrel 8 of the first turret.

The ring 267 encircles a boss 272 on the disc 216, and is held tightly against the face of said disc by a coil spring 273 arranged between a stop collar 274 and the ring 267. The stop is adjustable to vary the tension of the spring. The ring 267 is connected to a collar 275 near the end of shaft 212 by a rod 276. The collar, held in place 65 by a stop collar 277, is rotatable with respect to the shaft and is oscillated by a link 278 which connects the collar with operating mechanism to be later described.

The cover blank magazine generally indicated 70 at 210 comprises a table 279 mounted by legs

280 on an extension table 281 from the table 2, and four upright gauge bars 282 adjustably mounted on the table 279 by screw and slot connections 283. The pile of superposed cover sheets rests on a plate or table 284 fixed to a supporting 5 bar 285. The supporting bar is of square cross section and is slidably guided in brackets 286 and 287 mounted on tables 279 and 281 respectively. Two coil springs 288, arranged between a cross bar 289 at the end of the supporting bar 285 and the table 281, tend to pull said supporting bar in an upward direction. To prevent upward movement of the supporting bar, an eccentric 290 on the bracket 287 is provided to frictionally hold the bar. The grip of the 15 eccentric is released at regular intervals by a lever 291 connected to operating mechanism to be later described, thereby permitting the springs 288 to pull the bar 285 upward for a distance approximately corresponding with the thickness of 20 a cover blank. When a new supply of cover blanks is to be inserted in the magazine, it is only necessary to press down on the table 284, the eccentric being so arranged that it does not interfere with downward movement of the supporting bar. A flexible guide 293 is attached to each gauge bar 282, and the guides are adjustable toward and from each other by means of adjusting screws 294 in the gauge bars. The 25 guides 293 carry pins 295 at their upper ends, the pins engaging the top of the pile of superposed cover blanks, thereby holding it in place.

In order to prevent sticking of the cover sheets and to assure the picking up of only one sheet by the mandrel, two compressed air nozzles 296 30 are provided adjacent the edge of the pile of cover blanks. As shown more particularly in Figs. 51 and 52, the nozzles are mounted on a cross piece 297 carried by one of the gauge bars 282, and a hose 298 connects each nozzle with a compressed air pipe 299, which, in turn, is connected with a suitable compressed air apparatus. Interposed in the pipe 299 is an on and off valve 300, connected by a link 301 with operating mechanism to be later described. The nozzles 40 45 296 discharge compressed air at regular intervals between a number of the uppermost sheets of the pile of superposed cover blanks to keep these sheets virtually floating and thereby prevent sticking of the same. When a mandrel is about to pick up the top blank of the pile, however, the compressed air is shut off for an instant by valve 300, so that the flow of compressed air will not interfere with the picking up of a blank.

The turret 209 now advances one step, and on the rotary path of the mandrel from its lowest to the next following position, a glue roller 302 rises, and the cover blank carried by said mandrel is wiped against the glue roller. The glue roller 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 mandrel. A lever 314 is pivoted on each arm 305 and said lever carries a comb 315. This comb comprises a mounting bar 316 and teeth 317 mounted thereon and engaging the glue roller in grooves between the sections 303. The comb is 5 mounted on the elbow levers 314 by thumb screws 318 for quick dismounting. One of the levers 314 has an extension lever 319 connected by a link 320 to one arm of an elbow lever 321 10 pivoted on the frame 306 and the other arm of said elbow lever is connected by a link 322 to an operating mechanism to be later described. A coil spring 323 is arranged between the link 320 and the frame 306 to normally hold the comb 15 retracted, that is, away from the mandrel. The glue roller 302, in retracted position, contacts with an adhesive applying roller 324, which is journaled in the adhesive receptacle 211, and rotates in the adhesive, and the film of glue on the 20 roller is regulated and evenly distributed by a roller 325, which is journaled in sliding blocks 326, and may be adjusted toward and from the roller 324 along the rails 327 by screws 328. The shafts of rollers 324 and 325 extend beyond the 25 adhesive receptacle on one side, and carry meshing gears 329 and 330 respectively. The gear 329 also meshes with a gear 331, which is rotatably mounted on a hub 332 on the frame 306, and a sprocket wheel 333 is attached to said gear. The 30 sprocket wheel 333 is driven by a sprocket chain 334 from another sprocket wheel 335 on the counter shaft 244, which is to be described later.

The glue roller 302 having received an even film of glue from the adhesive applying roller 334, is swung toward the mandrel 224 at the proper time and the face of the cover blank on said mandrel is wiped against the roller, which thereby applies a film of adhesive to the cover blank. At the same time, the comb 315 rises 40 with respect to the roller 302 and the teeth of said comb are wiped against the face of the cover blank, thereby preventing the glue applied by one section 303 to run together with that applied by the adjacent section 303. In this 45 manner, adhesive is applied in stripes corresponding to the width of the sections 303 and said stripes being separated by narrow stripes of clean space.

If a mandrel should, for any reason, fail to pick 50 up a cover blank, a mechanism is provided to prevent the swinging glue roller 302 from rising and applying glue to the face of the mandrel. A valve 336 (Fig. 36) is provided on each of the 55 four mandrels 224 of turret 209, the valve having an extension or pin 337 and being normally held in closed position by a coil spring 338. If a cover blank has been picked up and the suction openings 255 of the gripper are closed by said cover blank, the valve 336 will be opened, that is, 60 sucked in, and the pin 337 will clear a mechanism, to be presently described, in its path to the glue applier. If, however, no blank has been picked up, the openings 255 will not be closed and the valve will, therefore, not be sucked in. As 65 shown in Fig. 49, a lever 338 is pivoted on an extension 339 on the table 1 and a link 340 connects the lever with one arm of an elbow lever 341 which is pivoted on a bracket extending from the adhesive pan 211. The other arm of said 70 elbow lever is pivotally connected to a slide 342, which is guided on the pan 211. If no cover blank has been picked up, the pin 337 will engage the lever 338 and thereby move the slide 342 toward the swinging arm 305. The slide 342, therefore, 75 will be in the path of a stop lug 343 on the arm

305, and the glue roller 302 will be prevented from rising and contacting with the mandrel. A coil spring 344 is arranged between the lever 338 and the extension 339 to normally hold the slide 342 away from the stop lug 343.

The mandrel 224 is finally projected radially toward the first turret to deposit its cover blank upon the bottom of the box on that mandrel of the first turret which has come to a stop at station IV. The cover blank with its glued face is tightly pressed against the box and any air that may be between the cover blank and the box can escape by means of the narrow stripes of clean space previously mentioned, thereby preventing the forming of bubbles. An upper and a lower folding roller now fold the upper and the lower extension of the cover blank onto the corresponding flanges of the box on the mandrel. As shown in Fig. 53 and Fig. 54, these folding rollers indicated at 345 are journaled in arms 346 fixed to parallel shafts 347, which in turn are journaled in a frame 348 mounted on the table 1. A gear 349 is fixed to each of the shafts 347 in such manner that the teeth of the same mesh with the teeth of rack bars 350 and 351 respectively, and the rack bars are held in engagement with the gears by guide members 352 and 353 on the frame. The rack bar 351 is fixed to the rack bar 350 and the latter is connected to a lever 354 pivoted on an extension 355 depending from the table 1. A coil spring 356 is arranged between the lever 354 and the leg 3 of the frame, to normally hold the folding rollers away from the flanges of the box, and a link 357 connects the lever 354 with operating mechanism to be later described.

As soon as a cover blank has been glued and pressed against the bottom of the box on the mandrel, the rack bar 350 is pulled downward and the rollers 345 sweep over the upper and lower flanges of the box, thereby folding the upper and lower extensions of the cover blank onto said flanges.

The first turret now advances to bring the mandrel in line with station V where a mechanism is provided to tightly press the upper and lower extensions of the blank onto the flanges of the box and to fold the flaps extending from the upper and lower extensions onto the side flanges of the box. This mechanism, as shown in Figs. 56 to 59 inclusive, comprises an upper and a lower pressing roller and four extension folding rollers. A plunger or presser plate 358 of substantially the same area as the bottom of the box, is provided to tightly press the cover blank against the box, and to hold it in place while the extensions are being pressed down. The upper and lower pressing rollers 359 are journaled in brackets 360 carried by angle pieces 361 connected to two arms 362 of a cross, and said angle pieces are adjustable toward and from each other by screw and slot connections 363. There are two pairs of folding rollers, one each adjacent each end of the two pressing rollers 359. The upper folding rollers 364 are journaled in brackets 365 carried by a cross head 366 connected to slide members 367 which are mounted to move in guides 368 on the face of mounting arms 369 connected to arms 370 of the cross previously mentioned. The mounting arms 369 are adjustable toward and from each other on the arms 370 by screw and slot connections 371. The two lower folding rollers 372 are journaled in brackets 373 carried by a crossbar 374, which is connected to slide members 375 mounted to move in the lower portion of the guides 368. Each slide 375 at its

lower end carries a pin 376 mounted to slide in a slot or track 377 in an arm 378, and both arms 378 are mounted on a cross head 379 which is fixed to a slide member 380 mounted to move in a vertical plane in a guide 381 extending from the table 1. A link 382 connects the slide 380 with operating mechanism to be described later. An upwardly extending rack bar 383 is attached to each slide 375 at 384, and a gear 385 is rotatably mounted near the upper end of the mounting arm 369 and on the rear face thereof, the teeth of said gear meshing with the teeth of the rack bar 383, and a rack bar 386 also meshing with the gear 385 is connected to the upper slide 367. If the slides 375, therefore, are moved upwardly, the motion is reversed by the gear and rack bar arrangement, and the slides 367 are thereby moved downwardly.

A roller 387, mounted on the lower arm 362 of the cross, runs on a track 388 supported by legs 389 on the table 1, and guides the cross in its path toward and from the mandrel. The plunger plate 358 is mounted on a bar 390 slidably mounted in a substantially U-shaped slide 391, which, in turn, is slidably supported in a bracket 392 extending from the table 1. The cross, composed of the members 362 and 370 previously mentioned, is secured to the slide or channel 391. A bracket 393, carried by the bar 390, is connected to one arm of an elbow lever 394 by an adjustable link 395, and a link 396 connects the other arm of the elbow lever 394 with operating mechanism to be later described. A coil spring 397, arranged between the lever 394 and the table 1, tends to move the plunger plate 358 toward the mandrel. A bracket 398 on the slide 391 is connected to a lever 399 by an adjustable link 400, and the lever 399 journaled in an extension from the table 1 is connected to an operating mechanism to be later described. The coil spring 397 is arranged to normally move the slide 391 and the folding mechanism attached to it toward the mandrel.

In operation, the plunger or presser 358 first contacts with the bottom of the box on the mandrel. The upper and lower pressing rollers 359 then move in to tightly press the upper and lower extensions of the blank onto the flanges of the box, and the extension folding rollers then sweep over the side extensions of the upper and lower flaps of the blank and fold them onto the sides of the box. The mandrel is now advanced to station VI where the remaining left and right extensions of the blank are folded onto the side flaps of the box, which is then transferred from its mandrel on the first turret to a mandrel on the second turret.

The mechanism for folding the side extensions and for transferring the box is shown in Figs. 63 to 67 inclusive. Two folding rollers 402 are mounted in a frame 403 which is secured to sliding bars 404. These bars are slidably supported by brackets 405 extending from the table 1, and a link 406 connects the frame 403 with an elbow lever 407, the other arm of which is connected to an operating mechanism to be later described. A coil spring 408 is arranged between the lever 407 and the table 1 so as to normally move the rollers 402 toward the box on the mandrel. The mechanism for transferring the box from a mandrel of the first turret to a mandrel of the second turret includes a pair of remover plates 409 of substantially the thickness of the body blank, which are arranged to engage the edge of the upper and lower side

flanges of the box. These plates are carried by extensions 410 from a supporting bracket 411 which is fixed to a sliding bar 412, slideable in brackets 413 carried by the table 1. A guide rod 414 mounted in brackets 415 is provided, and an extension from the bracket 411 slides on this rod to properly balance the bracket. A link 416 connects the sliding bar 412 with an elbow lever 417 journaled on the table 1 and said elbow lever is connected to an operating mechanism to be later described.

As soon as a box on a mandrel of the first turret is in line with station VI, the rollers 402 are moved forward and thereby fold and press the side extensions of the cover blank on the box onto the side flanges of the same. The remover plates 409 then engage the edge of the upper and the lower flange of the box, the suction on the mandrel of the first turret is shut off by a means previously described, a mandrel 20 of the second turret moves in position to receive the box, and the plates 409 push the box away from the mandrel of the first turret and onto the mandrel of the second turret, where the box is then held by suction.

The extensions of the cover blank are considerably longer than the flanges of the body blank, and these extensions therefore project beyond the edges of the flanges. To give a neat finish to the box, these projections are turned 30 in onto the inner faces of the flanges, and this operation is performed on the second turret, the box being transferred at station VI from the first to the second turret, so that the mandrels of the first turret provide a box supply mechanism for the die or hollow mandrel of the second turret.

The second turret (Figs. 67 to 71) comprises a shaft 418 journaled in a vertical bearing 419 on the table 1, and carrying at its upper end a hub 420. The hub is provided with three radial arms, and each arm is extensible and contractible, comprising an inner cylindrical member 421 connected with the hub, and an outer tubular member 422 slideable on the inner member. The outer member 422 of each arm carries at its outer end a hollow mandrel, die, or box shaping receptacle, indicated generally at 423, rotatable in an endless path. The outer member is held from rotation on the inner member, by key plates 424 which are secured to the hub, and extend above the arms. Each outer member has a cross plate 425 secured to the inner end thereof and on the upper face, and these plates co-operate with the key plates to prevent turning of the outer member.

Each of the mandrels is composed of a bottom, which has a pneumatic gripper opening in its outer face, and side and end walls 426 and 427 respectively. The side and end walls form with the bottom an open rectangular receptacle, of a size to receive the box from mandrel 8 with the open end of the box outward. The side and end walls are adjustably connected, by means of angle plates 428 having screw and slot connections 429 with the sides and ends. The hub 420 of the turret is provided with an arc shaped channel 430 which is connected by hose 431, with passages 432 near the outer ends of the outer members 422. This passage terminates 70 in the gripper opening in the face of the mandrel, and pressure is thus transmitted from the source of supply, to the face of the mandrel, to hold the box in place in the mandrel by suction. In order to transfer a box from a mandrel of 75

the first turret to a registering mandrel of the second turret, the mandrels are moved together, and mechanism is provided for moving that mandrel of the second turret which is at station VII toward the mandrel of the first turret which is at station VI. The said mechanism includes a bell crank 433, which is pivoted at 434 to the table 1. A link 435 connects one arm of the bell crank with a slide 436 movable in a guide 437 extending radially from a flanged collar 438 held on the upper end of bearing 419. A ring 439 is supported by the flange of the collar just below the hub, and this ring is provided in its upper face with an annular groove 440, forming a trackway, in which rotate rollers 441 journaled on the outer members 422 of the mandrel arms. The engagement of the rollers with the annular groove prevents outward movement of the members 422 of the arms, except when a mandrel is at station VII. At this point a switch plate 442 is interposed in the trackway 440, being arranged in a radial recess 443 in the disc. The switch plate is secured to the slide 436 and moves therewith, and it has a groove in its upper face concentric with the shaft 418, for receiving the roller 441 of that mandrel arm which is at station VII.

When a mandrel of the first turret is at station VI, the mandrel of the second turret which registers therewith is moved radially toward the mandrel of the first turret. The mandrels 8 and 423 are of such relative size that the hollow mandrel or die 423 may surround the periphery of mandrel 8 and leave a space between said periphery and the die so that the mandrel 423 will fit over the formed box on the mandrel of the first turret. At this moment the suction is cut off from the mandrel at station VI of the first turret, and turned on to the mandrel at station VII of the second turret. A valve 418a in the form of a disc is mounted to oscillate in the hub 420 of the turret. The valve has an arc shaped groove or passage 419a substantially 180° in length, and adapted to place the hose 431 of that mandrel, which is at station VII, in communication with a supply pipe 420a from the suction apparatus, and to retain said parts in communication until the mandrel passes station VIII. When the valve is in the position of Fig. 70, the adjacent end of the passage 419a is just out of register with the hose 431 of the mandrel at station VII. When the mandrel at this station is moved toward the mandrel at station VI of the first turret, and just before the mandrel 423 reaches the end of its outward movement, an upstanding lug on an arm 445, adjustably secured to slide 436, engages a depending pin 444 on the valve, and shifts the valve far enough to connect the passage 419a with hose 431 of the mandrel at station VII. At station IX the suction is released, the inner end of the hose 431 coming into register with a port 421a communicating with the atmosphere. The valve is returned to normal position by a coil spring 422a arranged between the valve and the ring. The valve is held in position within the ring 439 by plate springs 423a, which are secured radially of the ring and engage beneath the valve. The valve is limited in its return movement by a depending pin 424a which engages one of the spring plates 423a. After the mandrel 423 has engaged outside the box at station VI of mandrel 8, and the suction is turned on, the mandrel is withdrawn, carrying with it the box or article, which has been shaped on the first

turret. The second turret is now rotated a third of a turn, to bring the box to station VIII where the edges of the cover blank, projecting beyond the sides and ends of the box, are turned in.

The projections of the cover blank are turned down upon the inner faces of the flaps by the mechanism shown in Figs. 72 to 78 inclusive. This mechanism consists of a sectional collapsible plunger normally collapsed to enter the box, and capable of being expanded before and after it has entered the box, thereby to turn in and secure the projections of the cover blank to the box. The plunger is composed of four similar sections, indicated at 446, supported by a substantially rectangular head 447, and movable radially of the head to expand and contract the plunger. The head has pairs of slots 448 extending parallel with diagonals of the head, and screws 449 are passed through the slots into engagement with the plunger sections. The head has diagonal ribs 448a, and the sections have grooves 449a fitting the ribs, thereby to guide the sections in their expanding and collapsing movement. The arrangement is such that the four sections of the plunger may simultaneously move away from each other or in the reverse direction. They are normally drawn together by springs 450 arranged between adjacent sections, and integral with each section is an arm or extension 451 extending through a slot 452 disposed parallel to and between the slots 448. Each extension 451 has a cam face 453, and rollers 454 are rotatably mounted in fork portions of the collar 455, to engage said faces 453. The collar 455 is mounted on a sleeve 456 encircling a shaft 457, to which the head 447 is secured. The sleeve is slidable in a bearing 458 carried by a bracket 459 on the table 1. Mounted on the bearing 458 is an upwardly extending bracket 460, and the head carries a pin 461 slidable in an opening in said bracket. An extension 462 of the collar 455 carries a similar pin 463, also slidable in an opening in the bracket 460. The head and the collar and parts connected therewith are thereby held from rotation. Connecting plates 464 are mounted on the outer ends of extensions 451, and links 465 are arranged between said plates and the fork members of the collar 455. Slot and screw connections 466, between said links and plates, permit their movement with respect to each other. The plates 464 are connected by means of links 467 with a split collar 468 on the shaft 457 remote from the head, and coil springs 469 are arranged between said split collar and the collar 455. The operative face of the plunger, that is, the face which is adjacent the box, is provided with a forwardly projecting rib 470 of a size to fit within the box when the plunger is collapsed. A link 471 connects a split collar 472 on the end of sleeve 456 with one arm of an elbow lever 473 journaled in a bracket 474 on the table 1, and the other arm of said lever is connected by a link 475 with operating mechanism to be described later. A link 476 connects a split collar 477 clamped to the end of shaft 457 with one arm of an elbow lever 478 journaled in a bracket 479 on the table 1, and the other arm of the lever is connected by a link 480 to an operating mechanism to be later described. The operation of the parts just described is as follows:

When a mandrel of the second turret comes into register with the plunger, the collar 455 is moved toward the mandrel and the plunger is ex-

panded by means of rollers 454 and inclined cam faces 453. At the same time the plunger is moved toward the mandrel, and it is sufficiently expanded so that the ribs 470 of the sections engage outside of the extended edge of the cover blank. At this point, the collar 455 is retracted with respect to the head, the plunger thereby collapses, and the extended edges of the cover blank are swept inwardly. Both the head and the collar then continue to move forward and the edges of the cover blank are turned over the edges of the flaps and into the box. Forward movement of the plunger is stopped, but the collar continues to move forward with respect to the head, expanding the plunger and thereby pressing the inturned edges of the cover blank tightly against the inner faces of the flaps. It will be noted that the rib 470, by its opposite faces, provides a combined finishing folder and presser for each section, and that the rib of each section is rectangular in exterior outline so as to nicely fit the corners of the box in the die and press the extension flaps nicely into said corners. The inner face of the rib, as shown in Fig. 76, is inclining outwardly in the direction from its inner toward its outer edge to facilitate engagement with the extending edge of the cover blank and camming of said edge transversely across the edge of the assemblage of flaps of the body blank. By this construction, in usual operation, the edge of the extending cover blank will be deflected inwardly by the inclined face of the rib as the rib approaches the die or hollow receptacle, when in expanded position, complete inward deflection of said edge being accomplished by movement of the sections transverse to the forward movement of the rib. After the edge of the cover blank has been turned in and pressed, the box is completed, and there remains only the removal or discharge of the box from the mandrel. This is accomplished at station IX, after the retreat of the collapsible plunger.

This mechanism, as shown in Figs. 79 to 81 inclusive, is supported by legs 481 from the table 1, and comprises a guide 482 mounted on said legs, and a slide 483 is mounted to move in the guide toward and from the second turret. This slide is operated by an elbow lever 484 journaled in a bracket on the table 1, one arm of said lever being connected to the slide by a link 485, and the other arm is connected by a link 486, with operating mechanism to be later described. A coil spring 487, arranged between said lever and an extension from the table 1, tends to normally move the slide toward the mandrel on the second turret. Brackets 488 are mounted on the slide 483 and carry bearings 489, which, in turn, support a shaft 490. This shaft is fixed in position at its end remote from the second turret by set screws 491 in the bearing 489. At its end adjacent to the second turret, the shaft carries a cross head 492, consisting of four pairs of slotted lugs 493 extending radially thereof. A series of four gripping arms 494 are disposed one between each pair of lugs, and said arms are adjustable toward and from each other by means of screws 495 and slots 496 in the lugs, to provide for boxes of different size. The arms 494 are journaled on the screws 495, and they are operated simultaneously by links 497 pivoted to lugs 498 extending radially from a sleeve 499 encircling the shaft 490. Pivot screws 500 and radial slots 501 in the lugs 498 permit adjustment of the links toward and from each other in accordance with the arms

494. The sleeve 499 is free to move back and forth on the shaft 490, and one end of a link 502 is pivoted to said sleeve, while its other end, together with one end of another link 503, is pivotally connected at 504 to an operating link 505. The other end of the link 503 is pivoted to that bearing 489 which is removed from the second turret. The link 505 is connected to an elbow lever 506 journaled in a bracket on the table 1, and connected by a link 507 with operating mechanism to be later described. A coil spring 508, arranged between said elbow lever and the table 1, tends to normally hold the sleeve 499 away from the cross head 492.

An ejector plate 509 is mounted on a rod 510, 15 slidably supported in extensions 511 from the bearings 489, the extreme end of the rod resting against a lug 512 carried by the guide 482. A coil spring 513, arranged between a collar 514 adjustably connected to the rod, and a stop 515 on the extension 511, serves to normally hold the end of the rod 510 in contact with the lug 512. An inclined chute 516 is disposed directly below the ejector plate 509, and an opening 517 in the table 1 permits passage of the discharged boxes. 25

The operation of the above described device is as follows: When a mandrel is in register with the discharging mechanism, the slide 483 is moved toward the mandrel. The forward movement of the cross head is stopped at this point, 30 while continued forward movement of the sleeve 499, in respect to the cross head, causes the gripping arms 494 to engage the outside of the box through cut-outs 518 in the sides and ends 427 and 426 of the mandrel 423, and to grip the 35 walls of the box. The slide 483 is now moved rearward, that is, away from the mandrel, and near the end of its rearward movement, the plate 509, which is stationary with respect to the grippers, engaging the edge of the walls of the 40 box, ejects the same from between the grippers. The box is dropped upon the chute 516, and discharged into a basket or other suitable receptacle 45 placed under said chute.

The driving mechanism for the several operative parts is shown more particularly in Figs. 2, 3, and 5. The shaft 24, before mentioned, is journaled in bearing brackets 519 on the lower table, and it is driven from a motor 520 mounted on a structure beneath the table 2. The shaft 50 of the motor has a pinion 521, which meshes with a gear wheel 522 on a shaft 523 of a suitable exhauster (not shown), for controlling the suction of the turrets, and another pinion 524 on the shaft 523 meshes with a gear wheel 525. The 55 gear wheel 525 is journaled on the frame, and carries a pinion 526, which meshes with a gear wheel 527 on the shaft 24. The gear wheel is loosely mounted on the shaft and a clutch mechanism 528 is provided to couple the gear wheel to 60 the shaft. The clutch is operated by mechanism indicated at 529. The shaft 24 is connected with the shaft 196, previously mentioned, by a sprocket and chain drive 530, and a shaft 531 is driven by bevel gears 532 from the shaft 24. The shaft 65 244, before mentioned, is driven by a gear arrangement 533 from the shaft 531. A pair of bevel gears 534 serve to drive a shaft 535 from the shaft 196, and a shaft 536 is driven by bevel gears 537 from the shaft 24. The link 49, before mentioned, is connected to a follower 538 (Fig. 18), journaled on the table 1, and a friction roller 539 on the follower engages the edge of a cam 540 on the shaft 196. The link 67 is connected to a follower 541 (Fig. 21), pivoted to an 70 75

extension from the table 2, and a friction roller 542 on the follower engages the edge of a cam 543 on the shaft 196. The link 58 is connected to a follower 544, journaled in a bracket on the table 2 (Fig. 22), and a friction roller 545 rides on the edge of a cam 546 on the shaft 24. The link 547, and a slotted follower 548 (Fig. 25), connected to said link, embraces the shaft 24. A friction roller 549 on the follower 548 engages the edge of a cam 550 on the shaft 24. The lever 109 (Fig. 23) is connected by a link 551 to a follower 552 (Fig. 26) embracing the shaft 24, and friction roller 553 engages the edge of a cam 554 on the shaft 24. The shaft 536 carries a sprocket 555, which meshes with the chain 141 (Fig. 27), and a ratchet arrangement indicated at 556 is provided on the shaft 536 for manual turning of the main drive shaft 24. The link 75, controlling the suction valve of the first turret, is connected, by a bell crank 557 pivoted on the table 1 (Fig. 32), to a follower 558 embracing the shaft 24, and a friction roller 559 on the follower engages the edge of a cam 560 on the shaft 24. A coil spring 561, arranged between the follower and the table 2, serves to hold the roller 559 in contact with the cam 560. The follower 278, before mentioned (Fig. 45), embraces the shaft 531, and a friction roller 561 on said follower engages the edge of a cam 562 on the shaft 531. A coil spring 563, arranged between the follower and the table 2, serves to hold the friction roller in engagement with the cam. The follower 322 (Fig. 44) carries a friction roller 564 engaging the edge of a cam 565 on the shaft 531. The link 301 (Figs. 34 and 46) is connected to a follower 566 pivoted at 567, and carrying a friction roller 568, which engages the edge of a cam 569 on shaft 531. A coil spring 570 arranged between the follower and the table 2 holds the friction roller in engagement with the cam. The operating lever 291, previously mentioned, (Figs. 34 and 47) is connected to a follower 571 by a link 572, the follower being pivoted at 573 and having a friction roller 574 in engagement with a cam 575 on shaft 531. A coil spring 576 between the follower and the table 2 serves to hold the friction roller in contact with the cam. The follower 312 (Fig. 48) embraces shaft 531 and carries a friction roller 577 in engagement with a cam 578 on shaft 531. The link 237 (Fig. 37) connects with a follower 579 pivoted on the table 2 and a friction roller 580 on said follower engages the edge of a cam 581 on shaft 531. A coil spring 582 is arranged between the follower and the table 2 to hold the friction roller in contact with the cam. The link 357 (Fig. 55) connects with a follower 583 embracing shaft 531 and carrying a friction roller 584 in engagement with a cam 585 on shaft 531. The link 382 (Fig. 62) connects with a follower 586 pivoted at 587 and carrying a friction roller 588 which engages the edge of a cam 589 on the shaft 196. The link 396 (Fig. 61) is connected to a follower 590 pivoted at 591 and carrying a friction roller 592, engaging a cam 593 on shaft 196. The lever 399 (Fig. 60) is connected to a link 594, which is pivoted at 595 to a disc 596 carried by a shaft 597. A mutilated gear 598 (Figs. 5 and 6), secured to shaft 597, intermittently meshes with another mutilated gear 599 on the shaft 535. A lever arm 600, secured to the lever 407 (Figs. 63 and 65), is connected by a link 601 to an elbow lever 602, pivoted on the table 1, and said elbow lever is connected to a follower 603 embracing the shaft 196. A friction roller 604, secured to the follower, engages the edge of a cam 605 on the shaft 196. A lever arm 606, secured to the arm 417 (Figs. 63 and 66), is connected to a follower 607 embracing shaft 196, and carrying a friction roller 608 engaging a cam 609 on the shaft 196. A coil spring 610 arranged between the follower and a bearing bracket on the table 1, tends to hold the friction roller 608 in contact with the edge of cam 609. The bell crank 433 (Figs. 67 and 71) is connected by a link 611 to a follower 612, pivoted at 613, and carrying a friction roller 614 in contact with the edge of a cam 615 on the shaft 196. Coil springs 616, arranged between the bell crank 433 and the table 1 and the guide 437 respectively, serve to keep the friction roller 614 in contact with cam 615. The link 475 (Fig. 77) is connected to a follower 617 pivoted at 618 and carrying a friction roller 619 in engagement with the edge of a cam 620 on the shaft 196. A coil spring 621 between the follower and table 1 holds the friction roller in contact with cam 620. The link 480 (Fig. 78) is connected to a follower 622, pivoted at 623 and carrying a friction roller 624 in contact with the edge of a cam 625 on the shaft 196. The link 486 (Fig. 80) is connected to an elbow lever 626, journaled at 627, and connected to a follower 628, embracing the shaft 196, and carrying a friction roller 629 engaging the edge of a cam 630 on the shaft 196. The link 507 (Fig. 81) is connected to an elbow lever 631, journaled at 632, and connected to a follower 633 embracing the shaft 196 and having a friction roller 634 in engagement with the edge of a cam 635 on the shaft 196. Intermittent movement of the second turret is controlled by a Geneva stop movement, shown more particularly in Figs. 2 and 3. The shaft 27 driven from shaft 24 by bevel gears 28, carries a sprocket 636, and a sprocket chain 637 transmits movement by means of another sprocket wheel 638 to a shaft 639. The Geneva stop movement, somewhat similar to that shown for the first turret, comprises a mutilated gear 640 secured to the vertical shaft 639, and a mutilated gear 641 secured to the shaft 418 of the turret. The gear wheel 641 has plain concave surfaces 642 arranged at angular intervals of 120 degrees on the edge thereof, and at each of these surfaces a stop 643 extends radially from the gear wheel. The wheel 640 has radial stops 644 at the ends of the teeth, and the engagement of the stops 643 with the stops 644 insures the meshing of the teeth of the wheel 640 with those of the wheel 641. For every complete rotation of the gear wheel 640, a third of a revolution is given to the wheel 641 and to the turret shaft, to bring the mandrels to the successive stations.

From the foregoing it will be noted that, as illustrated and described, a step-by-step motion is imparted to both turrets. Six mandrels form a part of the first turret and these mandrels are successively brought to positions adjacent a corresponding number of stations. At the first of the stations suitable mechanism assures the bringing of a body blank to a position adjacent the mandrel, which thereupon retains such blank. At the second station the mechanism for this purpose not alone breaks down the blank but serves to retain the several surfaces thereof properly disposed with respect to each other. At the third station a properly formed and coated stay strip is applied to the folded boxes so that the parts thereof are supported and rigidified. At the fourth station the previously treated cover

blank or sheet is applied to the box and opposite side edges thereof are caused to lie parallel to and in contact with the side walls of the box blank. At the fifth station those parts of the inwardly folded side walls of the covering blank which extend beyond the end walls of the box are folded inwardly and caused to contact with the corresponding side or end flanges of the box body. At the sixth station those portions of the covering sheet which extend beyond the wall flanges are caused to be folded parallel to and in contact with such flanges and to overlie the end portions of the cover blank side walls which at the previous station have been folded inwardly. It is at this latter station that the box is transferred to that mandrel of the second turret which is disposed adjacent such station. The latter turret has three mandrels which successively occupy three different stations. The first is the transfer station mentioned. At the second station the edges of the covering sheet are turned inwardly and secured to the inner faces of the sides and ends of the box body, and at the third station the completed box is removed from the mandrel.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A forming machine including means to mount a body blank, means to fold such blank, means including a movably mounted adhesive roll for treating a covering blank having extended corner portions, means for moving said adhesive roll to and from adhesive applying position with reference to said covering blank, means for applying such covering blank to said folded blank, and with the corner portions thereof projecting beyond said body blank, means for folding said corner portions towards the folded portions of said body blank, means to cause the end portions of said covering blank to thereupon overlie said corner portions, both the side and end portions of said covering blank extending beyond the outstanding edges of said body blank and means to overlap said extending edge portions to enclose the edge of said body blank.

2. A forming machine including means to mount a body blank, means to fold such blank, means for applying a stay strip to the folded blank, means for treating a covering blank having extended corner portions, means for thereupon applying such covering blank over the stay strip to said folded blank, and with the corner portions thereof projecting beyond said body blank, means for folding said corner portions towards the folded portions of said body blank, means to cause the end portions of said covering blank to thereupon overlie said corner portions, both the side and end portions of said covering blank extending beyond the outstanding edges of said body blank and means to overlap said extending edge portions to enclose the edge of said body blank.

3. A forming machine including means to mount a body blank, means to fold such blank, means including a movably mounted adhesive roll for treating a covering blank having extended corner portions, means for moving said

adhesive roll to and from adhesive applying position with reference to said covering blank, means to prevent movement of said roll into adhesive applying position in the absence of a body blank on said mounting means, means for applying such covering blank to said folded blank, and with the corner portions thereof projecting beyond said body blank, means for folding said corner portions towards the folded portions of said body blank, means to cause the end portions of said covering blank to thereupon overlie said corner portions, both the side and end portions of said covering blank extending beyond the outstanding edges of said body blank, means to overlap said extending edge portions to enclose the edge of said body blank and means to cause the inwardly extending edge portions of said covering blank to contact with the inner faces of the side walls of said body blank.

4. A forming machine including means to mount a body blank, means to fold such blank, oscillatively mounted adhesive applicator for treating a covering blank, means for applying such covering blank to said folded blank and means for thereupon folding said covering blank to have its surfaces lie adjacent the folded surfaces of said body blank.

5. A forming machine including a mandrel carried by a rotary turret to mount a body blank, means to fold such blank, a pneumatic support for a covering blank of the size and shape of the covering blank, means for treating a covering blank, means for applying such covering blank carried by said pneumatic support to said folded blank, such covering blank being of an area greater than said body blank, means for folding said covering blank to have its surfaces extend adjacent to the surfaces of said body blank with the excess portions of said covering blank extending beyond the corresponding surfaces of said folded blank, said covering blank including extended corner portions and means for folding said corner portions to lie adjacent corresponding surfaces of said body blank.

6. A forming machine including means to mount a body blank, means to fold such blank, means for treating a covering blank, means for applying such covering blank to said folded blank, such covering blank being of an area greater than said body blank, means for folding said covering blank to have its surfaces extend adjacent to the surfaces of said body blank with the excess portions of said covering blank extending beyond the corresponding surfaces of said folded blank, said covering blank including extended corner portions, means for folding said corner portions to lie adjacent corresponding surfaces of said body blank and means for thereupon folding an extended portion of said covering blank to overlie and contact with said corner portions.

7. A forming machine including means to receive a body blank, means to fold said blank, means to apply a stay strip to the folded surfaces of said blank, means for receiving and applying a covering blank to said body blank and means for thereupon folding portions of said covering blank into contact with said stay strip.

8. A forming machine including means to receive a body blank, means to fold said blank, means to apply a stay strip to the folded surfaces of said blank, means for applying a covering blank to said body blank, said covering blank having an area greater than said folding blank, means for thereupon folding portions of said covering blank

into contact with said stay strip, excess portions of said covering blank extending beyond the corresponding portions of said body blank and means for causing said excess portions to be folded 5 inwardly and into contact with the inner surfaces of said body blank.

9. A forming machine including means to receive a body blank, means to fold said body blank, means to apply a stay strip to the folded surfaces 10 of said blank, means for applying a covering blank to said body blank, said covering blank having an area greater than said folding blank, means for thereupon folding portions of said covering blank into contact with said stay strip, the excess portions of said covering blank extending beyond the adjacent surfaces of said body blank and said covering blank including extended corner portions, means for folding said corner portions into 15 contact with said stay strip and means for enclosing said corner portions with one of the extended surfaces of said covering blank.

10. A forming machine including means to receive a body blank, means to fold said body blank, means to apply a stay strip to the folded surfaces 20 of said blank, means for applying a covering blank to said body blank, said covering blank having an area greater than said folded blank, means for thereupon folding portions of said covering blank into contact with said stay strip, the excess portions of said covering blank extending beyond the adjacent surfaces of said body blank and said covering blank including extended corner portions, means for folding said corner portions into 25 contact with said stay strip, means for enclosing said corner portions with one of the extended surfaces of said covering blank and means for thereupon causing the portions of the covering blank which extend beyond the body blank to enclose 30 the corresponding portions of the latter.

40 11. A forming machine including a turret, a head associated with said turret, means including movably mounted plates simultaneously engageable with the bottom and side walls of a body blank to apply said blank to said head, means for retaining said blank in association with said head, means cooperating with said head for folding such blank, means for receiving and delivering to the body blank upon such head a covering blank and means thereupon cooperating with said head to 45 fold said covering blank to extend adjacent the surfaces of said body blank.

50 12. A forming machine including a turret, a head associated with said turret, means to apply a body blank to said head, means for retaining said blank in association with said head, means cooperating with said head for folding such blank, means for receiving and delivering to the body blank upon such head a covering blank, means thereupon cooperating with said head to fold said 55 covering blank to extend adjacent the surfaces of said body blank, a further turret, a head forming a part of the same, means for transferring the blank from the head of the first turret to the head of said further turret and means cooperating with said further turret and means cooperating with said latter head to cause excess portions of said 60 covering blank to enclose adjacent surfaces of said body blank.

65 13. In a machine of the character described, in combination, a mandrel carried by a rotary turret for mounting a body blank, pneumatic supporting means for supporting a cover blank, means for rendering adhesive a cover blank carried on said supporting means, and means for thereafter adhesively applying said cover blank to a body blank 70 carried by its mounting mandrel.

75 14. In a machine of the character described, in combination, means for mounting a body blank, a plurality of rotatively mounted angularly spaced pneumatic supports for supporting cover blanks, means for rendering adhesive a cover blank carried on one of said supports, and means for thereafter adhesively applying said cover blank to a body blank carried by its mounting means. 5

15. In a machine of the character described, in combination, means for mounting a body blank, 10 pneumatic supporting means for supporting a cover blank, an oscillatory adhesive roll, means for moving said roll into position so as to apply adhesive to a cover blank on said supporting means, and means for thereafter adhesively applying 15 said cover blank to a body blank carried by its mounting means.

16. In a machine of the character described, in combination, means for mounting a body blank, pneumatic supporting means for supporting a 20 cover blank, an oscillatory adhesive roll, means for moving said roll into position so as to apply adhesive to a cover blank on said supporting means, means for thereafter adhesively applying 25 said cover blank to a body blank carried by its mounting means, and means for preventing movement of said adhesive means into applying position in the absence of a cover blank on its said supporting means.

30 17. In a machine of the character described, in combination, means for mounting a body blank, a plurality of rotatively mounted pneumatic supports for supporting cover blanks and oscillatively mounted adhesive roll, means for moving said roll into position so as to apply adhesive thereby 35 to a cover blank on one of said pneumatic supports, and means for thereafter adhesively applying said cover blank to a body blank carried by its mounting means. 5

40 18. In a machine of the character described, in combination, means for mounting a body blank, a plurality of rotatively mounted pneumatic supports for supporting cover blanks, an oscillatively mounted adhesive roll, means for moving said roll into position so as to apply adhesive thereby 45 to a cover blank on one of said pneumatic supports, means for thereafter adhesively applying said cover blank to a body blank carried by its mounting means, and means for preventing movement of said adhesive means into applying position in the absence of a cover blank on its said supporting means. 50

55 19. In a machine of the character described, in combination, supporting means for supporting a cover blank, said supporting means including a marginal extension terminating short of an adjacent edge of the supporting means whereby the latter is of a size and shape corresponding to said blank, means for rendering adhesive a cover blank carried by said supporting means, and means for thereafter adhesively applying said cover blank 60 to a body blank. 60

65 20. In a machine of the character described, in combination, supporting means for supporting a cover blank, said supporting means including a generally rectangular blank supporting surface with notches at the corners whereby it conforms in shape to said blank, means for rendering adhesive a cover blank carried by said supporting means, means for thereafter adhesively applying 70 said cover blank to a body blank, and means for causing said adhesive means to be inoperative in the absence of a cover blank on said supporting means.

75 21. In a machine of the character described, in 75

- combination, a plurality of rotatively mounted angularly spaced blank supports each having a blank supporting surface outwardly directed away from the axis of rotation, an oscillatably mounted adhesive roll, movable in the plane of rotation of said blank supports, and means for moving said roll into position so as to apply adhesive to blanks carried by said blank supporting surfaces.
22. In a machine of the character described, in combination, a plurality of rotatively mounted angularly spaced pneumatic blank supports, an oscillatively mounted adhesive roll, means for moving said roll into position so as to apply adhesive to blanks carried by said blank supports, and pneumatic means pneumatically connected to each of said blank supports for preventing movement of said adhesive means into applying position in the absence of a cover blank on its said supporting means.
23. In a machine of the character described, in combination, a plurality of rotatively mounted angularly spaced pneumatic blank supports, an oscillatively mounted adhesive roll, means for moving said roll into position so as to apply adhesive to blanks carried by said blank supports, and a pneumatic means controlled by said blank supports for preventing movement of said adhesive means into applying position in the absence of a cover blank on the blank support.
24. In a machine of the character described, in combination, a pneumatic blank supporting head including a generally rectangular blank supporting surface with notches at the corners whereby it conforms in shape to the blank supported thereby, said head having blank supporting sections mounted for movement relatively to each other.
25. In a machine of the character described, in combination, a pneumatic blank supporting head including a generally rectangular blank supporting surface, and a supplemental blank supporting surface extending along a margin of said rectangular surface and terminating short of an adjacent edge of the rectangular surface.
26. In a machine of the character described, in combination, a pneumatic blank supporting head including a generally rectangular blank supporting surface, a supplemental blank supporting surface extending along a margin of said rectangular surface and terminating short of an adjacent edge of the rectangular surface, and separate pneumatic controls connected respectively to said rectangular surface and to said supplemental surface.
27. In a machine of the character described, in combination, a pneumatic blank supporting head including a generally rectangular blank supporting surface, and a supplemental blank supporting surface extending along a margin of said rectangular surface and terminating short of an adjacent edge of the rectangular surface, said supporting head being formed oppositely to said supplemental surface with notched corner portions.
28. In a machine of the character described, in combination, a pneumatic blank supporting head including a generally rectangular blank supporting surface, a supplemental blank supporting surface extending along a margin of said rectangular surface and terminating short of an adjacent edge of the rectangular surface, said supporting head being formed oppositely to said supplemental surface with notched corner portions, and separate pneumatic controls connect-
- ed respectively to said rectangular surface and to said supplemental surface.
29. In a machine of the character described, in combination, a rotatably mounted blank support, means for retaining a blank upon said support for rotation therewith, and a swingably mounted adhesive applicator swingable in the plane of rotation of said blank support to and from adhesive applying contact with a blank on said support.
30. In a machine of the character described, in combination, a rotatably mounted blank support, means for retaining a blank upon said support for rotation therewith, a swingably mounted adhesive applicator swingable in the plane of rotation of said blank support to and from adhesive applying contact with a blank on said support, and means for controlling said blank support for picking blanks from a supply source.
31. In a machine of the character described, in combination, a rotatably mounted blank support, means for retaining a blank upon said support for rotation therewith, a swingably mounted adhesive applicator swingable in the plane of rotation of said blank support to and from adhesive applying contact with a blank on said support, and means for applying blanks to said blank support in sequence with operation of said adhesive applicator.
32. In a machine of the character described, in combination, a rotatably mounted blank support, means for retaining a blank upon said support for rotation therewith, a swingably mounted adhesive applicator swingable in the plane of rotation of said blank support to and from adhesive applying contact with a blank on said support, means for controlling said blank support for picking blanks from a supply source, and means for preventing movement of said adhesive applicator into applying position in the absence of a blank on said blank support.
33. In a machine of the character described, in combination, a rotatably mounted blank support, means for retaining a blank upon said support for rotation therewith, a swingably mounted adhesive applicator swingable in the plane of rotation of said blank support to and from adhesive applying contact with a blank on said support, means for applying blanks to said blank support in sequence with operation of said adhesive applicator, and means for preventing movement of said adhesive applicator into applying position in the absence of a blank on said blank support.
34. In a machine of the character described, in combination, a rotatably mounted blank support having a flat blank supporting surface outwardly directed away from its axis of rotation, means for retaining a blank on said support for rotation therewith, and a swingably mounted adhesive applicator swingable in the plane of rotation of said blank support to and from adhesive applying contact with a blank on the support.
35. In a machine of the character described, in combination, a rotatably mounted blank support having a flat blank supporting surface outwardly directed away from its axis of rotation, means for retaining a blank upon said support for rotation therewith, a swingably mounted adhesive applicator swingable in the plane of rotation of said blank support to and from adhesive applying contact with a blank on the support, and means for applying blanks to said blank support.

- support in sequence with operation of said adhesive applicator.
36. In a machine of the character described, in combination, a rotatably mounted blank support having a flat blank supporting surface outwardly directed away from its axis of rotation, means for retaining a blank upon said support for rotation therewith, a swingably mounted adhesive applicator swingable in the plane of rotation of said blank support to and from adhesive applying contact with a blank on the support, means for applying blanks to said blank support in sequence with operation of said adhesive applicator and means for preventing movement of said adhesive applicator into applying position in the absence of a blank on said blank support.
37. In a machine of the character described, in combination, a rotatably mounted blank support, pneumatic means for retaining a blank upon said support for rotation therewith, a swingably mounted adhesive applicator swingable in the plane of rotation of said blank support to and from adhesive applying contact with a blank on the support, and means for controlling said blank support for pneumatic adhering engagement thereof with blanks of a supply source.
38. In a machine of the character described, in combination, a plurality of angularly spaced arms carried by a rotary support and each carrying a blank support, means for retaining blanks on each of said blank supports, and a swingably mounted adhesive applicator swingable in the plane of rotation of said blank supports to and from adhesive applying contact with blanks carried by said supports.
39. In a machine of the character described, in combination, a plurality of angularly spaced arms carried by a rotary support and each carrying a pneumatic blank supporting head for pneumatically retaining blanks in position thereon, and a swingably mounted adhesive applicator swingable in the plane of rotation of said blank supporting heads to and from adhesive applying contact with blanks carried by said heads.
40. In a machine of the character described, in combination, a plurality of angularly spaced arms carried by a rotary support and each carrying a blank support, means for retaining blanks on each of said blank supports, a swingably mounted adhesive applicator swingable in the plane of rotation of said blank supports to and from adhesive applying contact with blanks carried by said supports, and means for operating said blank supports for successively picking blanks from a supply source.
41. In a machine of the character described, in combination, a plurality of angularly spaced arms carried by a rotary support and each carrying a pneumatic blank supporting head for pneumatically retaining blanks in position thereon, a swingably mounted adhesive applicator swingable in the plane of rotation of said blank supporting heads to and from adhesive applying contact with blanks carried by said heads, and means for controlling said pneumatic heads for successively picking blanks from a source and retaining them in position on the heads during adhesive application.
42. In a machine of the character described, in combination, a plurality of angularly spaced arms carried by a rotary support and each carrying a pneumatic blank supporting head for pneumatically retaining blanks in position thereon, a swingably mounted adhesive applicator swingable in the plane of rotation of said blank supporting heads to and from adhesive applying contact with blanks carried by said heads, means for controlling said pneumatic heads for successively picking blanks from a source and retaining them in position on the heads during adhesive application.
43. In a machine of the character described, in combination, a blank magazine, means normally urging blanks in the magazine toward delivery position, means including a blank support rotatable in an endless path for successively removing blanks from the magazine, and means whereby said blank support limits movements of said blank urging means.
44. In a machine of the character described, in combination, a stationary blank magazine, means normally urging blanks in the magazine toward delivery position, means for successively removing blanks from the magazine, means whereby said blank removing means limits movements of said blank urging means, and means for intermittently rendering said urging means operative to move the blanks toward delivery position.
45. In a machine of the character described, in combination, a blank magazine, means normally urging blanks in the magazine toward delivery position, a holding device including a rotary holding member having an eccentric holding surface for holding said urging means against blank moving action, and means intermittently releasing said holding device.
46. In a machine of the character described, in combination, a blank magazine, means normally urging blanks in the magazine toward delivery position, a holding device for holding said urging means against blank moving action, means intermittently releasing said holding device, and means including a member rotatable in an endless path for limiting to a predetermined distance the movement of the blanks in the magazine under action of said urging means when said holding device is released.
47. In a machine of the character described, in combination, a blank magazine, means normally urging blanks in the magazine toward delivery position, a holding device for holding said urging means against blank moving action, means intermittently releasing said holding device, blank removing means movable at intervals in an endless path to engage a blank in the magazine and to limit movement of the blanks under influence of said urging means when said holding device is released.
48. In a machine of the character described, in combination, a blank magazine, means normally urging blanks in the magazine toward delivery position, a holding device for holding said urging means against blank moving action, means intermittently releasing said holding device, a rotatably mounted pneumatic blank removing head movable at intervals in an endless path into engagement with a blank in said magazine whereby the blank is pneumatically supported by the head, and means whereby said head limits movement of the blanks by said urging means when said holding device is released.
49. In a machine of the character described, in combination, a stationary blank magazine, means normally urging blanks in the magazine

- toward delivery position, intermittently operated means for limiting movements of said blank urging means, means rotatable in an endless path for successively removing blanks from the magazine, and means whereby said blank removing means limits movements of said blank urging means.
5. In a machine of the character described, in combination, blank magazine, means normally urging blanks in the magazine toward delivery position, a blank removing device for removing blanks from said magazine and including a blank supporting head rotatable in an endless path, and means controlled by said blank supporting head for controlling the operation of said urging means.
10. In a machine of the character described, in combination, blank magazine, a blank removing device rotatable in an endless path for removing blanks from said magazine, and means controlled by said blank removing device for feeding the blanks in said magazine.
15. In a machine of the character described, in combination, a pair of turret heads, means for associating a blank with each of said heads, means to operate upon the blank secured to one such head and blank controlled means for rendering such operating means inoperative in the absence of a proper blank applied to the other 20 of said heads.
25. In a machine of the character described, in combination, a pair of turrets, mounted for rotation in intersecting planes, heads forming a part of said turrets, means for supplying articles to the head of one of said turrets, means for supplying further articles to the head of the other turret, means for shifting said turrets to have the heads thereof occupy positions adjacent each other, and means acting when said heads are in 30 such position to project one of said heads against another and to simultaneously remove one of the second named articles from the head with which it is associated and to apply the same to an article supported by the other said head.
35. In a machine of the character described, in combination, a pair of turrets, mounted for rotation in intersecting planes, heads forming a part of said turrets, means for supplying articles to the head of one of said turrets, means for supplying further articles to the head of the other turret, means for shifting said turrets to have the heads thereof occupy positions adjacent each other, and means acting when said heads are in 40 such position to project one of said heads against another and to simultaneously remove one of the second named articles from the head with which it is associated and to apply the same to an article supported by the other said head.
45. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in 50 such position to project one of said heads against another and to simultaneously remove one of the second named articles from the head with which it is associated and to apply the same to an article supported by the other said head, and a swingably mounted applicator acting prior to said last named means to treat each further 55 article so that the latter will remain associated with the article to which it is applied.
55. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in 60 such position to project one of said heads against another and to simultaneously remove one of the second named articles from the head with which it is associated and to apply the same to an article supported by the other said head, and means acting subsequently to fold one of said articles over the edge of the other article and to press it into permanent contact with oppositely disposed surfaces of the latter.
65. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in 70 such position to project one of said heads against another and to simultaneously remove one of the second named articles from the head with which it is associated and to apply the same to an article supported by the other said head, and means acting subsequently to fold one of said articles over the edge of the other article and to press it into permanent contact with oppositely disposed surfaces of the latter.
75. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in 80 such position to project one of said heads against another and to simultaneously remove one of the second named articles from the head with which it is associated and to apply the same to an article supported by the other said head, and means acting subsequently to fold one of said articles over the edge of the other article and to press it into permanent contact with oppositely disposed surfaces of the latter.
- treat each further article so that the latter will remain associated with the article to which it is applied, and automatic article controlled means for rendering said treating means inoperative in the absence of articles associated with either of said heads.
56. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in such position to project one of said heads against another and to simultaneously remove one of the second named articles from the head with which it is associated and to apply the same to an article supported by the other said head, means acting prior to said last named means to treat each 10 further article so that the latter will remain associated with the article to which it is applied, and automatic article controlled means for rendering said treating means inoperative to cooperate with such further article and with the head normally supporting the latter in the event that no article is supported by said latter head.
57. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in such position to remove one of the second named articles from the head with which it is associated and to apply the same to an article supported by the other said head, means acting prior to said last named means to treat each further article so that the latter will remain associated with the article to which it is applied, and means controlled by said articles for rendering said treating means inoperative to cooperate with such further article and with the head normally supporting the latter in the event that no article is supported by said first named head.
58. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in such position to remove one of the second named articles from the head with which it is associated and to apply the same to an article supported by the other said head, and means acting subsequently to fold one of said articles over the edge of the other article and to press it into permanent contact with oppositely disposed surfaces of the latter.
59. In a machine of the character described, in combination, a pair of turrets, heads forming a part of said turrets, means for supplying articles to the head of one of said turrets, means for supplying further articles to the head of the other turret, means for shifting said turrets to have the heads thereof occupy positions adjacent each other, means acting when said heads are in such position to project one of said heads against another and to simultaneously remove one of the second named articles from the head with which it is associated and to apply the same to an article supported by the other said head, and means acting subsequently to fold one of said articles over the edge of the other article and to press it into permanent contact with oppositely disposed surfaces of the latter.

cle supported by the other said head, means acting subsequently to fold one of said articles over the edge of the other article and to press it into permanent contact with oppositely disposed surfaces of the latter, and means acting thereupon to discharge the assembled articles.

60. An applying machine including, in combination, a pair of rotary turrets, heads associated with each of said turrets, means for supplying articles to the head of one turret, means for supplying other articles to the head of the second turret, means for retaining the articles applied to such heads, means for rotating said turrets to occupy positions adjacent each other, means for treating an article carried by one of said turrets to render it adhesive, means for projecting the head of the second turret relatively to the turret to transfer an article carried thereby and to adhesively attach it to an article carried by the head of the first turret whereby to assemble such articles and means for discharging the assembled articles.

61. An assembling machine including, in combination, a pair of rotary turrets, a head associated with the first of said turrets, a head slidably mounted by the second turret, means for rotating said turrets to bring said heads from remote positions to positions adjacent each other, means for supplying articles to the head of said first turret, a source of article supply for the head of the second turret, means for periodically projecting the head of said second turret into contact with the source of article supply and also towards the article associated with said first head, and means connected to said projected head to retain in association therewith an article engaged thereby.

62. In a machine of the character described, in combination, a source of article supply, a head, a support, means for slidably mounting said head with respect to said support, means for shifting said head to overlie said source, means for projecting said head towards said source of article supply, means for thereupon shifting said support and head to a position overlying a further article, means for treating one of said articles for adhesive attachment with the other, and means for again projecting said head to cause adhesive contact between the article carried thereby and the further article.

63. In a machine of the character described, in combination, a source of article supply, a head, a support, means for slidably mounting said head with respect to said support, means for shifting said head to overlie said source, means for projecting said head towards said source of article supply, so as to pick an article therefrom, means for maintaining said article in association with said head, means for treating said article to render it adhesive, and means for projecting said head to adhesively attach said article to another article.

64. In a machine of the character described, in combination, a pair of rotary turrets having their axes of rotation angularly disposed to each other, means for rotating said turrets in unison, blank supporting heads carried by said turrets, means for adhesively treating a blank on one of said heads, and means for transferring a blank carried by one head and adhesively applying it to a blank on a head of the other turret.

65. In a machine of the character described, in combination, a pneumatic blank supporting head, including adjacent pneumatic blank supporting

surfaces mounted for movement relatively to each other.

66. In a machine of the character described, in combination, a pneumatic blank supporting head, including adjacent pneumatic blank supporting surfaces mounted for movement relatively to each other and normally positioned adjacent to each other to form a substantially continuous blank supporting surface.

67. In a machine of the character described, in combination, a pneumatic blank supporting head, including adjacent pneumatic blank supporting surfaces mounted for movement relatively to each other and normally positioned adjacent to each other to form a substantially continuous blank supporting surface, and means for adhesively treating a blank supported by said surfaces when in their said normal positions.

68. In a machine of the character described, in combination, a pneumatic blank supporting head, including adjacent pneumatic blank supporting surfaces mounted for movement relatively to each other and normally positioned adjacent to each other to form a substantially continuous blank supporting surface, means for adhesively treating a blank supported by said surfaces when in their said normal positions, and means for subsequently moving one of said surfaces relatively to the other to adhesively apply said treated blank.

69. In a machine of the character described, in combination, a pneumatic blank supporting head, including adjacent pneumatic blank supporting surfaces mounted for movement relatively to each other, and separate pneumatic controls connected respectively to said supporting surfaces.

70. In a machine of the character described, in combination, a pneumatic blank supporting head, including adjacent pneumatic blank supporting surfaces mounted for movement relatively to each other and normally positioned adjacent to each other to form a substantially continuous blank supporting surface, and separate pneumatic controls connected respectively to said supporting surfaces.

71. In a machine of the character described, in combination, a pneumatic blank supporting head, including adjacent pneumatic blank supporting surfaces mounted for movement relatively to each other and normally positioned adjacent to each other to form a substantially continuous blank supporting surface, separate pneumatic controls connected respectively to said supporting surfaces, and means for adhesively treating a blank supported by said surfaces when in their normal positions.

72. In a machine of the character described, in combination, a pneumatic blank supporting head, including adjacent pneumatic blank supporting surfaces mounted for movement relatively to each other and normally positioned adjacent to each other to form a substantially continuous blank supporting surface, separate pneumatic controls connected respectively to said supporting surfaces, means for adhesively treating a blank supported by said surfaces when in their normal positions, and means for subsequently moving one of said surfaces relatively to the other to adhesively apply said treated blank.

73. In a machine of the character described, in combination, supporting means for supporting a box blank having a head wall and side and end walls, a mandrel for supporting a cover blank with marginal extensions, means for operating said mandrel for adhesively applying the cover

- blank carried thereby to a box blank on said supporting means, and means for adhesively applying said blank marginal extensions to the outside and inside of said side and end walls.
- 5 74. In a machine of the character described, in combination, supporting means for supporting a box blank having a head wall and side and end walls, a mandrel for supporting a cover blank with marginal extensions, means for adhesively treating said cover blank and its marginal extensions in position upon said mandrel, means for operating said mandrel for adhesively applying the cover blank carried thereby to a box blank on said supporting means, and means 10 for adhesively applying said blank marginal extensions to the outside and inside of said side and end walls.
- 15 75. In a machine of the character described, in combination, supporting means for supporting a box blank having a head wall and side and end walls, a mandrel for supporting a cover blank with marginal extensions, means for operating said mandrel for adhesively applying the cover blank carried thereby to a box blank on said supporting means, means for turning and adhesively applying the terminal portions of certain of said marginal blank extensions, and means for adhesively applying said blank marginal extensions to the outside and inside of said side and end walls.
- 20 76. In a machine of the character described, in combination, supporting means for supporting a box blank having a head wall and side and end walls, a mandrel for supporting a cover blank with marginal extensions, means for adhesively treating said cover blank and its marginal extensions in position upon said mandrel, means for operating said mandrel for adhesively applying the cover blank carried thereby to a box blank on said supporting means, means for turning terminal portions of certain of said marginal blank extensions and adhesively applying them to adjacent walls of the box blank, and means for adhesively applying said blank marginal extensions to the outside and inside of said side and end walls.
- 25 77. In a machine of the character described, in combination, supporting means for supporting a box blank having a head wall and side and end walls, a mandrel for supporting a cover blank with marginal extensions, means for operating said mandrel for adhesively applying the cover blank carried thereby to a box blank on said supporting means, means for retaining said cover blank upon said mandrel substantially stationary with reference thereto, means for adhesively applying the cover blank on said mandrel to a box blank to a box blank, and means for folding said blank extensions over the outside of said side and end walls and adhesively applying them to the inside thereof.
- 30 78. In a machine of the character described, in combination, supporting means for supporting a box blank having a head wall and side and end walls, a mandrel for supporting a cover blank with marginal extensions, means for operating said mandrel for adhesively applying the cover blank carried thereby to a box blank on said supporting means, means for retaining said cover blank upon said mandrel substantially stationary with reference thereto, means for adhesively treating said cover blank on said mandrel, means for operating said mandrel for adhesively applying the cover blank carried thereby to a box blank on said supporting means, and means for adhesively applying said blank marginal extensions to the outside and inside of said side and end walls.
- 35 79. In a machine of the character described, in combination, supporting means for supporting a box blank having a head wall and side and end walls, a mandrel for supporting a cover blank with marginal extensions, means for operating said mandrel for adhesively applying the cover blank carried thereby to a box blank on said supporting means, means for retaining said cover blank upon said mandrel substantially stationary with reference thereto, means for adhesively treating said cover blank on said mandrel, means for rotating and translating said mandrel for adhesively applying the cover blank carried thereby to a box blank on said supporting means, and means for adhesively applying said blank marginal extensions to the outside and inside of said side and end walls.
- 40 80. In a machine of the character described, in combination, supporting means for supporting a box blank having a head wall and side and end walls, a mandrel for supporting a cover blank with marginal extensions, said mandrel being of a size and proportions to engage and support said cover blank and its marginal extensions, means for retaining said cover blank on said mandrel substantially stationary with reference thereto, means for adhesively treating said cover blank on said mandrel, means for adhesively applying said cover blank on said mandrel to a box blank, and means for adhesively applying said blank marginal extensions to the outside and inside of said side and end walls.
- 45 81. In a machine of the character described, in combination, supporting means for supporting a box blank having a head wall and side and end walls, a mandrel for supporting a cover blank with marginal extensions, said mandrel being of a size and proportions to engage and support said cover blank and its marginal extensions, means for controlling said mandrel to pick up cover blanks one at a time, means for retaining said cover blanks upon said mandrel substantially stationary with reference thereto, means for rotating said mandrel to carry said cover blank to applying position, means for adhesively treating said cover blank on said mandrel, means for operating said mandrel to apply the blank thereon to a box blank, and means for folding said blank extensions over the outside of said side and end walls and adhesively applying them to the inside thereof.
- 50 82. In a machine of the character described, in combination, a pneumatic blank supporting head including separate adjacent blank supporting sections, means for moving one of said supporting sections with reference to another, and a pneumatic blank control connected to said last mentioned section.
- 55 83. An applying machine including a pair of rotary turrets, heads forming a part of each of such turrets, means for delivering material to each such head, means for transferring and applying the material from one such head to the material associated with the second head, means for coating the transferred material prior to its application to the material supported by the second head and means for rendering such coating means inoperative in the absence of material.
- 60 HAROLD C. COPPINS.
